UNITED STATES PATENT OFFICE

2,281,548

AUTOMATIC PHONOGRAPH

Edward F. Andrews, Chicago, Ill.

Application June 17, 1938, Serial No. 214,310

61 Claims. (Cl. 274—10)

This invention relates to automatic phonographs and has for its principal object to provide an improved phonograph which is adapted to operate automatically for the playing of one or a plurality of records.

One of the objects of the invention is to provide an automatic phonograph which is relatively small and compact and which is, nevertheless, adapted for the playing of any selected number of a large number of records.

—A further object of the invention is to provide an automatic phonograph of this type which is adapted to play either or both sides of any desired number of records.

A further object of the invention is to provide an improved automatic phonograph which is adapted to playing a predetermined number of recordings desired, and to play recordings which have been selected, and to play a sequence of recordings in the event that no selection has been made.

Other objects, advantages and capabilities of the invention will appear from the following description of a preferred embodiment thereof taken in conjunction with the accompanying drawings, in which:

Fig. 1 is a plan view of a phonograph embodying the invention, the view being taken in section through the cabinet in which the machine is enclosed with a record in playing position, and a driving motor being omitted, better to illustrate other details. The driving motor is illustrated in Fig. 2.

Fig. 2 is a side elevation of the machine as viewed from the left-hand side (i. e., the left side when viewing Fig. 1 from the right or selector end), a portion of the mechanism at the extreme front of the machine being cut away and certain end supports being omitted, better to illustrate operating parts of the record magazine drive and the record selector mechanism.

Fig. 3 is a rear elevation of the machine with the driving motor and part of its support being omitted.

Fig. 4 is a fragmentary elevation view of a portion of the main frame member of the machine as viewed from the right and generally along the line 4—4 of Fig. 1 with no records on the turntable and the record magazine omitted.

Fig. 5 is a similar fragmentary view as viewed from the left and generally along the line 5—5 of Fig. 1, showing a record in playing position and the player arm shifted to the opposite side of the record from that occupied by it in Fig. 1.

Fig. 6 is a view similar to Fig. 5, showing the

relation of elements when the record has been returned to its magazine.

Fig. 7 is a fragmentary sectional view, the section being taken on the line 7—7 of Fig. 1 and illustrating more particularly the player arm shifting mechanism.

Fig. 8 is a similar fragmentary sectional view, the section being taken on the line 8—8 of Fig. 1 and illustrating more particularly the trip mechanism.

Fig. 9 is a sectional plan view taken on the line 9—9 of Fig. 2, showing the mechanism for arresting the magazine at record playing positions.

15 Fig. 10 is a sectional detail view taken on the line 10—10 of Fig. 9, showing the manner in which the magazine is arrested in playing alignment with the record transfer mechanism and turntable by successive record selecting stops when none of the stops is selectively actuated.

Fig. 11 is a similar view showing the manner in which the stop mechanism is released after the return of a record from the turntable to the magazine to permit the magazine to proceed to the next stop.

Fig. 12 is a view similar to Fig. 10 showing the relation of the stop mechanism parts when one or more of the stop bars has been selectively actuated.

30 Fig. 13 is a similar view showing the manner in which one of the stop bars is operated to initial or unactuated position.

Fig. 13a is a sectional detail view through the mechanism shown in Fig. 10, the section being taken on the line 13a—13a of Fig. 9.

Fig. 14 is a fragmentary sectional view taken on the line 14—14 of Fig. 3, showing in detail the adjustable stops for the player arm.

40 Fig. 15 is a sectional detail view taken on the line 15—15 of Fig. 3, showing the reversing switch controlling the direction of rotation of the drive motor and various parts driven thereby, which switch is actuated at the limits of movement of the record magazine.

Fig. 16 is a sectional detail view taken on the line 16—16 of Fig. 5, showing the main cam shaft and cams and the magazine drive clutch in cross-section.

50 Fig. 17 is a diagrammatic view of the drive for the cams and the magazine.

Fig. 18 is a fragmentary sectional view taken on the line 18—18 of Fig. 5, showing the turntable members and associated parts in record gripping relation.

55

Fig. 19 is a similar view showing said parts in record releasing relation.

Fig. 20 is a fragmentary sectional view of the player arm operating mechanism with the player arm in playing engagement with a record, the section being taken on the line 20-20 of Fig. 3.

Fig. 21 is a similar view showing the parts in different relation and more specifically with the player arm out of engagement with a record and positioned for shifting the player arm from one side of the record playing plane to the other.

Fig. 22 is a sectional detail showing a resilient connection between the turntable shaft and the turntable drive gear taken on the line 22-22 of Fig. 18.

Fig. 23 is a sectional plan similar to Fig. 9 showing a modified form of record selecting mechanism.

Fig. 24 is a vertical section taken therethrough on the line 24-24 of Fig. 23 showing the mechanism stopped by an actuated selector member.

Figs. 25 and 26 are similar views showing the parts in different relations.

Fig. 25 shows the mechanism released after the return of the actuated selector and ready to move to another position.

Fig. 26 shows the mechanism conditioned to play the records successively when no selectors are actuated.

Figs. 27 and 28 are sectional detail views taken on the line 27-27 of Fig. 24. Fig. 27 shows the mechanism in position to arrest the magazine to play a record selected by actuation of a record selector button. It thus corresponds to Fig. 24. Fig. 28 shows the mechanism in position to arrest the magazine to play successive records when no record has been selected. It thus corresponds to Fig. 26.

Fig. 29 is a fragmentary sectional plan detail showing the preferred arrangement of the control buttons in this embodiment of the invention on the front of a cabinet housing the phonograph.

Fig. 30 is a wiring diagram showing the electrical connections which may be employed in the foregoing embodiments of the invention.

Fig. 31 is a fragmentary side elevational view illustrating an embodiment of the invention in which two pickups are employed, each to play only its corresponding side of records.

Fig. 32 is a plan view thereof.

Fig. 33 is a sectional detail view taken on the line 33-33 of Fig. 31 and showing part of the player arm mounting and actuating mechanism.

Fig. 34 is a sectional detail view, the section being taken on the line 34-34 of Fig. 32 and illustrating further details of the player arm mounting and actuating mechanism.

Fig. 35 is a perspective view of a cam member shown in Figs. 32 to 34, inclusive, and

Fig. 36 is a wiring diagram illustrating connections employed in the embodiment of the invention shown in Figs. 31 to 35, inclusive, for selectively shunting the particular player arm pickup not in use.

Referring to the drawings, the reference numeral 30 designates a cabinet which encloses the phonograph mechanism with the exception of the selector buttons 31 and bars 32 which carry these buttons, the bars extending through a front wall 33 of the cabinet. The bars 32 extend rearwardly and their inner ends are received in slots 34 formed in a bar 35 which forms part of the base 36 of the machine. The carrying frame is provided with a pair of transverse rail

formations 37, upon which ride rollers 38 of the magazine 39. The base 36 is provided with a rearward extension 40 which terminates in a bracket 41 which supports the motor 42 in an oblique position as best seen in Fig. 2. A main frame member 43 extends upwardly from the base portion 40 as best seen in Fig. 2, this frame member being preferably in the form of a substantial plate which serves as a support for practically all mechanisms of the phonograph with the exception of the selector mechanism, the magazine and the elements associated therewith.

The magazine 39 comprises a lower channel member 44 to which are secured two end plates 45 of concave formation (Fig. 2). The upper and outer extremities of the two end plates 45 are connected by bars 46. These bars extend through openings in spacer plates 47 which are of generally triangular form as best seen in Fig. 2. The spacer plates are maintained in vertical parallel space relation by means of spacer collars 48 through which pass the rods 49. As best seen in Fig. 3 the spacer collars 48 and the plates 47 are arranged in alternate order on the rods 49, so that the plates 47 provide magazine pockets for the records. When the records are located in these pockets they stand vertically, each being supported by a pair of the spacer collars 48. The plates 47, a pair of which is located one upon each side of each record, serves to maintain the records in vertical position and in uniformly spaced relation. In the embodiment of the invention illustrated twenty records, of the same diameter, for example, ten-inch records, are mounted in the magazine. It will be understood, however, that the magazine can be readily adapted for a greater or lesser number of records.

The magazine 39 is adapted for transverse movement to an extent at least equal to the distance between the two extreme records in the magazine. This movement enables each record of the magazine to be brought to a substantially central position defined by two turn table elements 49 and 50, so that each record of the magazine may be brought into position to be delivered between the two turn table elements for playing, as is best seen in Fig. 1. The buttons 31 and the stop bars 32 are provided in number double that of the record spaces in the magazine, so that in the embodiment of the invention illustrated forty buttons 31 and bars 32 are provided. The twenty buttons 31 on the left-hand side of the machine constitute a group which corresponds to the recordings on the right-hand sides of the records in the magazine. The twenty buttons 31 on the right-hand side constitute a group which corresponds to the recordings on the left-hand sides of the records in the magazine. Suitable indicia (not shown) may be associated with each button so as to identify the recording with which it is associated.

As has previously been indicated, the magazine is supported by the rollers 38 which are mounted on a channel member 44. The channel member 44 carries on its under side a pair of rollers 51 which ride in a transverse slot 52 provided in the base member 36. The cradle member 44 also carries, adjacent its center, a depending member 53 which extends through the slot 52 and carries a nut 54. The nut 54 receives a screw 55 which is rotatably mounted in bearings 56 which depend from the under side

of the base 36. The screw 55 is driven in one direction or the other by means of a pulley 57, over which passes a belt 58 driven in manner hereinafter to be described. A portion of the screw 55 extends beyond one of the bearings 56, being that bearing shown on the left-hand side of Fig. 3. This extension of the screw 55, which is designated by the reference numeral 66, is provided with a fine thread as is best shown in Fig. 15. Upon the threaded extension 10 66 is mounted a nut 59 which is held against rotation by suitable means, for example, by means of a rod 60 which extends into a slot 61 in the nut. The nut 59 is provided with two projections 62 which are located in alignment 15 with the arm 63 of a switch 64. It will readily be understood that when the screw 55 is rotated so as to cause the nut 54 to move in one direction, for example, upwardly as viewed in Fig. 15, the nut 59 will also move upwardly but at a 20 much lower speed.

When the nut 54 has reached the end of its travel, the lower projection 62 will have engaged the arm 63 of the switch 64 and swung it upwardly to such an extent that the switch is 25 snapped, the handle being then in the dotted line position shown in Fig. 15. The switch 64 is connected to the motor in such a way that this actuation of the switch causes reversal of the motor with the result that the nut 54 moves in opposite direction, that is, downwardly as is viewed in Fig. 15, and the nut 59 moves in similar direction, its other projection 62 becoming operative to swing the switch arm 63 back towards its full line position, whereupon 30 the switch snaps over and again reverses the direction of the motor. The position of the nut 54 at which reversal of the motor occurs can be adjusted by means of contact screws 65 which are mounted in the projection 62. This adjustment should be such that every one of the records in the magazine 39 must be located opposite the record playing position defined by the turntable elements 49 and 50 during each continuous movement of the magazine.

It may here be noted that the switch 64 is a double pole double throw switch of the toggle type and that it controls two circuits which insure the operation of the motor 42 in opposite directions. Thus the motor 42 may be a shaded pole motor having two shading windings, one of which is adapted to be closed by the switch 64 in one position, and the other of which is adapted to be closed by the switch 64 in its other position. Of course, any known type of reversing motor may be employed if desired. Thus, as shown in Fig. 30, a reversible motor 42 of the capacitor type may be employed, the capacitor associated with the motor being designated by the reference numeral 42'. When the arm 63 of the switch is snapped into the position shown in the full lines of Fig. 15, the motor drives the turntable elements in counter-clockwise direction as viewed in Fig. 2. As a result of this motion the nut 59 will move towards the dotted line position as shown in Fig. 15, and as this motion brings the nut 59 slightly above its position as shown in Fig. 15, the switch 64 snaps to reverse the motor and cause rotation of the turn table elements 49 and 50 in clockwise direction as viewed in Fig. 2.

Between the two plates 45 of the magazine extends a round bar 67 which is located in the forward part of the magazine 39, the bar 67 being located below and slightly rearwardly of the front

bar 46. A bail 68 comprising a main straight portion and two small end portions is pivotally mounted on the bar 67 by means of openings in the end portions. As best seen in Fig. 9, these end portions are located adjacent the walls 45 of the magazine 39, being separated therefrom by means of washers 69. Upon the bar 67 on the inner sides at the ends of the bail 68 are freely mounted two sleeves 70. At their adjacent ends the sleeves 70 are provided with flanges 71 which are separated by a spacing sleeve 72, which like the sleeves 70, is slidable longitudinally upon the bar 67. As best seen in Fig. 9, the lengths of the sleeves 70 and the sleeve 72 are such that together they are somewhat shorter than the distance between the ends of the bail 68, the difference being at least equal to the width of one of the bars 32. Adjacent their outermost ends the sleeves 70 rigidly carry arms 73 which extend downwardly and are bent outwardly slightly with respect to their bosses whereby they are mounted on sleeves 70. A coil spring 74 is mounted around the sleeve 72 and is adapted to bear against the adjacent end flanges of the sleeves 70. When, however, one of these sleeves is arrested, the magazine being in movement, which arrestment is effected in the manner hereinafter described, the spring 74 is compressed and the two end flanges of the sleeves 70 bear against the sleeve 72. Upon each sleeve 70 is rotatably mounted a sleeve 75 which is held against longitudinal movement by the inner end flange on the sleeve 70 and the boss of the arm 73 at the other end of the sleeve 70. Each sleeve 75 has rigidly mounted thereon a forwardly extending pin 76 which normally rests upon the upper edge of a bar 77 which extends along the whole length of the series of bars 32 as best seen in Fig. 1. The bar 77 is pivotally mounted by means of arms 78 at its 40 opposite ends on a bar 79 which is rigidly mounted on brackets 80 carried by the frame 36. Each outer sleeve 75 carries a clevis 81 on which is pivotally mounted a dog 82. Each dog 82 extends outwardly in the longitudinal direction and its outer end is provided with a flat detent face 83 which is adapted to engage the bars 32 in the manner hereinafter more particularly described with reference to Figs. 10, 11, 12 and 13.

Each inner sleeve 70 carries a rearwardly projecting radial rod 84, the outer end of which is slotted at 85 as best seen in Figs. 10, 11, 12, 13 and 13a. These slots 85 receive the bar 68 and are so arranged that the sleeves 70 and 75 may move to a limited extent on the bar 67 without disturbing the location of the bar 68 within the slots 85. The rod 84 extends through an arcuate slot 86 in the outer sleeve 75. This slot has a certain limited length so that when the bar 68 is moved within certain limits in either direction, the outer sleeves 75 and the elements mounted thereon remain stationary. When, however, the bar 68 is subjected to a greater movement the pins 84 will engage the ends of the slots 86 and cause sleeves 75 to rotate with the sleeves 70. The bar 68, the pins 84 and the inner sleeves 70 are biased to the position shown in Figs. 10, 12 and 13a by means of springs 91 which may be anchored to the bar 68 and to any suitable part of the magazine framework. The outer sleeve 75, together with the rod 76 and the dog 82 are resiliently biased in the clockwise direction as viewed in Figs. 10, 11, 12 and 13, for example, by means of a spring 93 which is secured to the outer sleeve 75 and to a stationary part of the magazine

38, for example, to one of the plates 47 as best seen in Fig. 2.

When no bar 32 is pushed inwardly the bar 77 has the position shown in Fig. 10. Consequently, if the magazine is moving toward the left, that is, the upper side as viewed in Fig. 9, the dog 82 on the left-hand sleeve 78 engages a detent 87 on the next bar 32. The arrestment of the left-hand sleeve 78 will result in compression of the spring 74 until further relative approaching movement of the two sleeves 78 is prevented by the intermediate sleeve 72. It will be noticed with reference to Fig. 9 that the left-hand arm 73 is now located in alignment with the bar 32 which arrested the magazine, whereas, the right-hand arm 73, which is in alignment with the right-hand end of the right-hand dog 82, is out of alignment with all the bars 32.

It may here be noted that after a record is played and is returned to the magazine a contact 88 on a swinging arm 89 engages the bar 68, thus rotating the dog 82 away from the detent 87 and into alignment with a recess 90 formed in the upper side of the bar 32 as shown in Fig. 11. Consequently the dog 82, together with the associated sleeves 78 and 70, are moved to the left, that is, in the upward direction as viewed in Fig. 9. The dog 82 is no longer held by the bar 32 which arrested it. It will be noted that during the movement of the pin 84 from its position in Fig. 10 to its position in Fig. 11, the arm 73 is brought into close propinquity to or contact with the bar 32 which arrested the magazine. Since this bar was not displaced from its normal position it is not actuated by the arm 73.

When one or more of the bars 32 are pressed inwardly the bar 77 is elevated to the position shown in Fig. 12. The resulting elevation of the pins 76 brings both the dogs 82 into the position shown in Fig. 11 or 12. Consequently these dogs will miss the bars 32 which have not been displaced inwardly, as will be understood from Fig. 11. Consequently movement of the magazine will take place, to the left, for example, until the left-hand dog 82 strikes a portion 92 of the first displaced bar 32 which it meets. Of course, it will be understood that when the magazine is moving to the left the right-hand dog 82 will merely slip over in bars 32 with which it comes into contact. During reverse movement, that is movement to the right, the right-hand dog 82 is effective in arresting the magazine and the left-hand dog 82 is inoperative. After the record corresponding to the rod 32 which has been displaced inwardly, as shown in Fig. 12, has been played, the contact member 88 of the arm 89 engages the bar 68 in the manner shown in Fig. 13 and the inside sleeve 70 is consequently rotated in the counter-clockwise direction and the arm 73 is likewise rotated. This arm engages the inner end of the inwardly displaced bar 32 and returns it to normal position. The outer sleeve 75 is unaffected in this operation and when the bar 32 moved backwardly the dog 82, the face 83 of which was bearing against the portion 92 of the arresting bar 32, moves slightly, bringing the effective end of the dog 82 into the recess 90 of the arresting bar 32. If more than one bar 32 has been displaced inwardly the bar 77 remains in elevated position and the dogs 82 remain in the radial direction they occupy in Figs. 12 and 13. If the last displaced bar 32 has been returned to its initial position, as shown in Fig. 13, the bar 77 drops downwardly and the dogs 82 tend to move towards the position shown in Fig.

10. The effective dog 82 does not attain this position, however, since it engages the forward side of the projection 87, being thus left free for co-operation with the next bar 32, when translation of the magazine is resumed.

The shaft 94 of the motor 42 extends upwardly and forwardly in oblique direction on the right-hand side of the main frame member 43 (see Fig. 2), this shaft being supported on suitable bearings (not shown). At its upper end the shaft 94 is provided with a worm gear 95 which meshes with a worm gear 96. The worm gear is hollow, comprising two complementary portions, one of which has a bearing portion 97, which provides 15 a relatively long bearing surface which is supported in a stationary bearing plate 98, as shown best in Figs. 18 and 19. The stationary bearing plate 98 is mounted in a plate 99 which is supported from the frame member 43 with the aid of projections 100 which maintains the plate 99 in parallel spaced relation to the frame member 43. Upon the outer side of the plate 99 are mounted hollow polished contact members 101.

A tubular member 102 extends freely through 25 the bearing portion 97 of the pinion 96 and through an opening 103 in the wall of the pinion opposite the bearing member 97. A rod 104 extends through the hollow pinion 96. This rod passes through an eye 105 of a spring member 30 106 (Fig. 22) located within the pinion 96. The spring member comprises two convolutions 107 which extend substantially completely around the sleeve 102. The extremities 108 of the spring member 106 are turned radially inwardly and are 35 located in openings 109 in the sleeve 102. Thus, while the sleeve 102 may move axially within pinion 96 to a limited extent, these two elements are operatively kept together so that the sleeve 102 may be rotated in either direction by the 40 pinion 96 through the resilient connection 106. Flexibility is, however, provided between the pinion 96 and the sleeve 102, so that any vibration or irregular torsional movements are not transmitted except through the resilient connection. The face of the pinion 96 opposite the bearing member 97 bears against a thrust bearing 110 mounted in the plate 43. A pinion 111 is rotatably mounted within this bearing and one of its faces is pressed towards the side of the pinion 96 by means of a spring 112. This spring abuts 45 a ring 113 carried by the sleeve 102.

The turntable member 49 is mounted on the right-hand side of the sleeve 102 and when the sleeve 102 is free to move to the left under the influence of the spring 112, the turntable member 49 is retracted from its operating position as 55 shown in Fig. 18 to the position shown in Fig. 19, in which the member 49 is drawn to the left-hand side, beyond the record contact members 101. In alignment with the turntable element 49 is the outer turntable element 50, which comprises a central stem portion 114 which is rotatably mounted in a bushing 115 in which it is held by suitable means, for example, by means of an expanded split ring 116.

The bearing 115 is rigidly mounted in an arm 117 which extends in substantial horizontal direction towards the rear of the machine (see Fig. 1). This arm is of sufficient length to provide clearance of the records 118 when moved into playing position and the turntable element 50 thereon defines the record playing position. The rearward end of the arm 117 is turned inwardly towards the frame plate 43 upon which it is rigidly mounted. The thrust applied by the

turntable element 49 upon the turntable element 50, during record playing, is communicated by the stem portion 114 of the turntable element 50 to a ball 119 which bears against a hardened plate 120 in the bottom of the bearing member 115.

A pin 121, which is the centering pin adapted to extend through the central opening of a record, is slidably mounted within the sleeve 102. This pin carries at its left-hand end a cup member 122. A helical spring 123 abuts against the left-hand end of the sleeve 102 and against the interior of the cup member 122. The cup 122 is engaged by a lever 124 which will be herein-after more particularly described. It is sufficient here to say that when the lever 124 is retracted as shown in Fig. 19, the springs 112 and 123 are extended. The turn table member 49 is thus retracted away from the turn table member 50 and the pin 121 is also retracted so that its pointed end 125 is drawn into the sleeve 102. The spring 123 is much weaker than the spring 112. Consequently, when the lever 124 is moved towards the turn table members 49 and 50 the spring 123 is first compressed and the pointed end 125 of the pin 124 is projected towards the turn table member 50 and its apex enters into the cavity 126 in the turn table member 50.

As the lever 124 is further actuated, that is, as it moves in the upper direction as viewed in Figs. 18 and 19, the stronger spring 112 is also compressed and the turn table member 49 is carried towards the turn table member 50 to such an extent that any record located between the turn table members is firmly gripped thereby as shown in Fig. 18.

The left-hand portion of the pinion 111 which is located on the left-hand side of the frame member 43 meshes with the pinion 127 (see Figs. 5, 16, and 17). The pinion 111 is splined or keyed to the sleeve 102 so that these two elements rotate together while axial movement of the sleeve is permitted as has just been described. The pinion 127 is mounted on a rod 128 carried by the frame member 43. The pinion 127 is integral with a small pinion 129. The pinion 129 meshes with the pinion 130 which is integrally mounted on a hub member 131 (Fig. 16), which in turn is mounted for free rotation on a shaft 132 carried by the frame member 43. The hub member 131 rigidly carries a notched wheel 133. The notched wheel 133 consequently rotates continuously when the motor 42 is operating.

The pinion 130 also meshes with a pinion 134 which is provided with a relatively large hub 135 whereby it is rotatably mounted on a sleeve 136 rigidly carried by the main frame member 43. A hub 137 is mounted on the shaft 132 alongside the hub 131 (see Fig. 16). Rigidly mounted on the hub 137 are a disc 138, a cam 139 and a further cam 140. The disc 138 is cut away as indicated at 141 (see Figs. 2 and 5). Adjacent the flattened part 141 the disc 138 has pivoted thereto a dog 142 which is located on the right-hand side of the disc 138 and is biased inwardly, so that its detent 143 engages the notched wheel 133. When this occurs the disc 138 is positively driven by the motor and consequently the cams 139 and 140 are rotated simultaneously with the disc 138.

The hub 135 of the pinion 134 is provided on opposite sides with recesses 144 which are flared in the outward direction. Also mounted on the sleeve 136 is a collar 145 which has camlike projections 146 complementary to the recesses 144.

5 The collar 145 is provided with a radially projecting pin 147. The collar 145 is normally biased towards the hub 135 of the pinion 134 by a coil spring 148 which extends around the free end 10 of the sleeve 136 and is received in a recess 149 in a pulley 150. This pulley is rigidly mounted on the end of the shaft 151, which is free to rotate and slide endwise in the sleeve 136. The pulley 150 is maintained in position by means 10 of an arm 153 which bears against a ball 154 located in a central recess in the end of the shaft 151. The belt 58 previously referred to extends over the pulley 150.

The pulley 150 is provided with one or more pins 155 which are directed towards the collar 145 and are so located that when the pulley 150 is forced inwardly by the arm 153, the pin 147 engages one of the pins 155 and drives the pulley 150. When the pulley 150 is prevented from rotation and the collar 145 is likewise held against rotation, then continued operation of the pinion 134 has the effect of moving the collar 145 to the right as viewed in Fig. 16, owing to the co-operation between the sloping sides of the recesses 144 and the corresponding projections 146. It may here be noted that the pulley 150 and the sleeve 145 become held against rotation when the magazine is arrested by the engagement of one of the dogs 82 with one of the bars 32.

30 The result of the outward movement of the collar 145, that is the movement to the right as viewed in Fig. 16, is that the arm 153 is moved outwardly with results which will hereinafter become more fully understood in the light of the 35 description of the operation of the machine which is hereinafter set forth. The arm 153 is one arm of a bell crank lever 156 which is pivotally mounted on base 40 by means of a screw 157. A spring 158 (see particularly Figs. 5 and 40 6) tends to move the arm 153 inwardly as viewed in Fig. 16. The other arm 153' of the bell crank lever 156 engages the lower arm of a lever 159 pivoted at 160 on the frame member 43. The upper end of the lever 159 is pressed by the spring 45 158 against the periphery of the disc 138.

When the flattened portion 141 of the disc 138 arrives in contact with the upper end of the lever 159, that upper end engages the tail of the dog 142 and withdraws its detent 143 out of contact with the notched wheel 133. When that occurs the rotation of the cams 139 and 140 is discontinued. The movement of the upper end of the lever 159 to the left as viewed in Fig. 2 rotates the bell crank lever 156 in the clockwise direction as viewed in plan Fig. 5. The resulting inward movement of the arm 153 moves the pulley 150 to the left as viewed in Fig. 16, bringing the pin 147 into engagement with one of the pins 155. Consequently the belt 58 is driven and the magazine translates until it is arrested in the manner described above. When that occurs the projection 146 effects the movement of the arm 153 to the right as viewed in Fig. 16, and this, as has just been described, results in clockwise rotation 60 of the lever 159. This movement of the lever 159 releases the tail of the dog 142 and the detent of this dog engages the notched wheel 133 so that rotation of the cams 139 and 140 is begun. As will hereinafter be more fully explained, these cams rotate for approximately one-half revolution and they are arrested, in the position in which they are shown in Fig. 2, during the playing of a recording.

70 The lever 124 is pivotally mounted on a bracket 161 carried by the main frame member 43 (see

Figs. 2, 5, and 6). The lever 124 carries a projecting arm 162 which is engaged by a spring 163 so as to compress the springs 123 and 112 and force the turn table spindle 121 and the turn table member 49 into record engaging position. The upper side of the arm 162 is engaged by an arm 164 of a three-armed member 165 which is pivotally mounted on a shaft 166. Another arm 167 of the three-armed member 165 bears against the underside of a projecting shoulder 168 of an arm 169. This arm is pivotally mounted on a bracket 170 on the frame member 43 and it is biased against the arm 167 by a spring 171. The third arm 172 of the three-armed member 165 carries a roller 173 which is adapted to cooperate with the cam 140.

It is to be noted that the roller 173 and the cam have the relation shown in Fig. 2 during a record playing and the relation shown in Fig. 6 when the record is returned to the magazine. It will be noted that in both cases the roller 173 is substantially symmetrical with respect to the cam 140. The result of this relation is that the three-armed member 165 is subjected to substantially the same movement during any consecutive half revolution of the cam, irrespective of the direction in which the cam is turning. It is to be noted that the same fact obtains between the roller 174 of the arm 175, which cooperates with the cam 139 (see also Figs. 2, 5, and 6).

The arm 175 is integral with the arm 176, both being pivotally mounted by means of a pin 177 on the main frame member 43. The arm 176 is provided adjacent its end with a slot 178. This slot receives a pin 179 carried by an arm 180 which is rigidly secured to a shaft 181 which extends through the main frame member 43 and is carried by a bearing 182 on the right side thereof (see Figs. 1 and 3). On the shaft 181 is mounted the record removing arm 89 and a record returning arm 183. These arms are in longitudinal alignment and operate in the record playing position which is defined by the turntable elements 49 and 50.

The shaft 181 is biased by a spring 184 so that the roller 174 tends always to remain in contact with the cam 139. When the roller 174 rolls down the fall on the cam 139, the spring 184 is sufficiently strong to rotate the record returning arm 183 in the clockwise direction as viewed in Fig. 2 and return the played record to the magazine. The arm 89 normally, that is at the end of playing and the return of the record to the magazine, occupies the position shown in dotted lines in Fig. 2. For this purpose the arm 89 extends into a position immediately above the frame member 44 and immediately below the records 118 in the magazine, that is the portion of the arm 89 adjacent the magazine enters this magazine between the rear rod 46 and the rear edge of the channel 44, and has sufficient space between these elements to move from the dotted to full line position shown in Fig. 2.

When the arm 89 is in the dotted line position shown in Fig. 2, the arm 183 extends in close propinquity to the rear curve of the aligned record in the magazine (see also Fig. 6). As the cam 139 makes a one-half revolution, the roller 174 moves outwardly thereon to a position similar to that shown in Fig. 2. Consequently, the arm 89 swings from its dotted line position in Fig. 2 to its full line position in that figure. Adjacent the free end the arm 89 is provided with a record-gripping formation. The record rolls over the rear rod 46, or rather over one of the spacer

elements 48 mounted thereon. The record rolls between the turn table element 50 and the polished contacting members 101 and it rests on the arm 183, which is provided with a suitable record engaging button at its end. After the arms 89 and 183 come to rest the pointed centering pin 121 is moved outwardly towards the turn table element 50. This pointed end enters the center opening of the record and cams it upwardly to an extent which is slight but at the same time sufficient to allow the record to rotate freely without contacting any part of the arm 183 or of the magazine. When the record is played the centering pin 121 and the turn table element 49 are retracted into their positions shown in Fig. 19. Consequently, the record which was held between the turn table elements 49 and 50 drops slightly coming into contact with one of the spacing elements 48 of the magazine and the arm 183.

Thereafter the arms 183 and 89 rotate in the clockwise direction as viewed in Fig. 6, returning the played record to the magazine. It is to be noted that after the record is returned the contact member 88 on the arm 89 engages the bar 68 in the manner and with the results hereinbefore described.

The player arm, or tone arm 185 is supported in a horizontal bearing 186 (see particularly Figs. 1, 20, and 21). This bearing may be in the form of a sleeve including anti-friction ball bearings 187 which provide for the very ready movement of the sleeve 188. The sleeve 188 is held against removal from the bearing 186 by means of a flange 189 at one end and a removable thrust bearing element 190 which is rigidly secured to the other end by means of a nut 199.

The sleeve 188 rigidly carries a horseshoe bracket 191. A shaft 192 extends through the sleeve 188 and through a bevel gear 193 which is located at the side of the bracket 191 remote from the bearing 186. The shaft 192 is keyed to the bevel gear 193 so that relative sliding movement is permitted between these elements, while the shaft 192 is enabled to drive the bevel gear 193. Between the bevel gear 193 and the side of the bracket 191 adjacent the bearing 186, the shaft 192 rigidly carries a cam member 194 in the form of a tapering collar rigidly mounted to the shaft 192 with the aid of a set screw. Beyond the collar 190 the shaft 192 is keyed to a pinion 195. This pinion is maintained against the left-hand end of the sleeve 188 by means of a spring 196 which abuts against the pinion 195 and against a collar 197 mounted on the shaft 192. The pinion 195 meshes with a sector 198 which is also pivotally mounted on the shaft 166.

The bevel gear 193 meshes with a bevel gear 200 which is integral with the sleeve 201. This sleeve is rotatably mounted in a sleeve 202 which is rigidly carried by the horseshoe bracket 191 with its axis at right angles to the shaft 192. Rotatably mounted on the exterior of the sleeve 202 is a sleeve 203, from which extends a pair of arms 204 which support the pivot 186a of the player arm 185. The bracket 191 carries a counterpoise weight 185a on the side of the shaft 192 removed from the player arm 185. The counterpoise 185a is of such mass that it balances the player arm in all its positions. The two sleeves 201 and 203 are rigidly connected together by means of a pin 205 which passes through a slot 206 in the sleeve 202. This slot extends around the circumference of the sleeve 201 for slightly more than 180° so that the rotation of the player

arm about the axis provided by the sleeve 202 is limited to 180°, the pin 205 engaging the sleeve 202 at the ends of the slot 206 so as to direct the needle 207 of the pickup 208 towards one side of the record 118 in playing position between the turntable elements 49 and 50, or towards the other side of the record.

A pin 209 is slidably located within the sleeve 201. The player arm 185 rigidly carries a short arm 210 which extends inwardly over the outer end of the pin 209. A spring 210a biases the arm 210 towards the pin 209 and consequently causes the pickup needle to bear against the record being played with a certain constant pressure.

The inner end of the pin 209 is adapted to be engaged by the cam member 194 when the shaft 192 is displaced in the upward direction as viewed in Fig. 20. It will readily be understood that when the shaft is thus displaced the pin 209 is moved to the right as viewed in that figure and the arm 210 is moved in similar direction, as shown in Fig. 21. Consequently, the player arm 185 is moved away from the record and this occurs irrespective of the side of the record with which the needle 207 is engaging.

Adjacent the bearing 186 the frame member 43 carries an enlargement 211 which is provided with a bore 212 which is parallel to the shaft 192. The bore 212 is provided with a shoulder 213 at its end adjacent the horseshoe bracket 191. A coil spring 214 bears against the shoulder 213 and against the shoulder formed on a plug 215 which is slidably mounted within the bore 212. The plug 215 is provided with a stepped bore 216 for the reception of a pin 217 which has a sharp point normally projecting from one end of the plug 215. The pin 217 has a head 218 which is located in the larger part of the bore 216 and normally is pressed against a shoulder in the bore by means of a spring 219. The spring 219 is held compressed by a rod 220 which is secured into the larger end of the bore 216.

It may here be noted that the shaft 192 and the plug 215 are displaced from their normal positions shown in Fig. 20 into the positions shown in Fig. 21 by means of the arm 169. It will be noted that when that displacement occurs the player arm 185 is moved away from the record. At the same time the pin 217 is brought into contact with the horseshoe bracket 191. It may be here noted that the bracket 191 is relatively broad and it is adapted to overlie the pin 217 in all its operative positions.

The engagement of the point of the pin 217 with the bracket 191 causes only a slight frictional force upon the bracket 191. It may here be noted that the bracket 191 is moved by the sector 198 before the playing of a record.

If the recording on the left-hand side of a record is played and a recording on the left-hand side of a record is to be played again, the movement of the sector 198 is such that the player arm is merely returned to initial playing position, that is moving in the reverse direction, to its course during the previous playing. If right-hand recording is followed by another right-hand recording, the same result is attained, the movement being, of course, in the opposite direction, as is necessary from the fact that the player arm is located on the opposite side of the record. When, however, a left-hand recording follows a right-hand recording, or a right-hand recording follows a left-hand recording, it is necessary for the player arm to rotate on the sleeve 202 through 180°.

The sector 198 is moved when the arm 169 is in the relation shown in Fig. 21. Consequently, the sector movement occurs when the player arm 185 is raised from the record and when the pin 217 is forced against the bracket 191. When the sector is moved the friction between the gears 193 and 200 is such that the player arm assembly moves as a whole and no rotation of the player arm relative to the sleeve 202 occurs. When, however, the pin 217 enters the recess 221 on the bracket 191, there is considerable resistance to the free movement of the player arm assembly and this resistance is sufficient to hold the assembly in definite position determined by the location of the recess 221 until the bevel gear 193 has driven the bevel gear 200 and effected the 180° which is necessary for changing from playing left-hand recordings to right-hand recordings or vice versa.

The recess 221 is located on the bracket 191, so that the arrestment of the player arm and the arcuate movement of the player arm occurs when the player arm is approximately at its highest position. It may also be noted that the arcuate path of the pickup is in the upward direction around the record playing position so that the movements of the record and the turning of the player arm may be effected simultaneously.

Referring more particularly to Figs. 2, 5, 6, and 7, it may be seen that sector 198 carries two integral arms 222 and 223 which are adapted to be engaged by a head 224, located between these arms, which head is carried at one end of a bell crank lever 225 which is pivotally mounted on a rod 226 carried by the frame member 43 by means of a post 227.

The end of the lever 225 remote from the head 224 is adapted to be engaged by one or the other of two pins 228 and 229 (Fig. 7) which are carried by the disc 138. The portion of the lever 225 remote from the head 224 is normally maintained substantially radial with respect to the axis of the cams 139 and 140. This result may suitably be attained by means of a spring 225a which is secured to a lug integral with the lever 225 and also secured to the frame member 43.

When the disc 138 rotates in the counter-clockwise direction, as viewed in Fig. 7, the pin 228 engages the lever 225 so as to swing it in clockwise direction. Consequently, the head 224 engages the arm 222 and swings the sector 198 downwardly, thus carrying the player arm downwardly into position for playing the right-hand side of the record. When, however, the disc 138 rotates in the clockwise direction, as viewed in Fig. 7, the pin 229 engages the lever 225 and swings the sector 198 upwardly. This upward movement carries the player arm upwardly. It is to be noted that the pins 228 and 229 are normally clear of the lever 225, and consequently during playing of a record the player arm and the sector 198 move freely and together.

It is advisable that the initial playing position of the player arm should be capable of adjustment with considerable accuracy. The player arm is arrested at initial playing position by the engagement of a pin 230, carried by the frame member 43 with one or another of two stops 231 which are pivotally mounted on the horseshoe bracket 191 as shown in Fig. 14. The stops 231 are pivotally mounted on this bracket (see Figs. 20 and 21) so that portions thereof project beyond the bracket into alignment with the pin 230. The stops 231 abut against set

screws 232 mounted in the bracket 191, and by very slight adjustment of these set screws it is possible to provide for the arrestment of the needle 207 precisely at initial playing position for the two sides of records.

It will be noted that the sector 198 carries the player arm back to or slightly beyond initial playing position. If the player arm is carried past initial playing position, it is returned to the correct position by the pin 230 engaging one of the stops 231 which are biased against the screws 232 by the springs 231a. Thus the player arm is returned to the correct initial playing position by the action of the springs 231a after the bell crank lever 225 has been returned to its neutral position by the spring 225a, leaving the sector 198 free.

Also mounted on the shaft 166 are two levers 233 and 234. The levers 233 and 234 are oppositely directed. At adjacent ends they are provided with detent formations 235 and 236 which are directed towards each other and which are located in cooperative relation with the periphery of the bearing element 190 which is rigidly secured to the sleeve 188, so that the bearing element 190 moves progressively with the player arm 185 as the latter is moved around the axis provided by the bearing 186.

The detents 235 and 236 are held against the periphery of the element 190 by means of a spring 237 which extends between the two levers 233 and 234, and holds both detents at all times in contact with the element 190. The element 190 is rigidly secured to the sleeve 188 so that it always rotates with the player arm 185 as that arm moves over the face of a record in playing position. The element 190 is provided with a peripheral recess 238 in alignment with the detents 235 and 236. The detents 235 and 236 are raised out of the recess on to the periphery of the member 190 on mere rotation of the element 190. When the player arm 185 is in the position shown in full lines in Fig. 5, that is, the initial position for playing the left-hand side of a record, then the detent 235 is located within the recess 238 and the detent 236 is riding on the periphery of the element 190.

During playing the player arm 185 moves downwardly over the record and when it reaches a position corresponding to the dotted line position in Fig. 5, that is, after the record has been played, the member 190 has rotated in the clockwise direction, as viewed in Fig. 5, sufficiently to permit the detent 236 to drop into the recess 238 as shown in Figs. 6, 7 and 8. When the right-hand side of a record is being played, for example, as shown in Fig. 2, the detent 236 is located in the recess 238 and the detent 235 is riding on the periphery of the element 190. As the record is played, the element 190 rotates in counter-clockwise direction, as viewed in Fig. 2, until, at a point where the record has been played, the detent 235 also drops into the recess 238.

When the detent 236 is riding on the periphery of the member 190, the opposite end of the lever 234 is in alignment with the end 239 of a hook member 240 which is suspended from the rod 226 as best seen in Fig. 5. When, however, the detent 235 is in engagement with the periphery of the member 190, as shown in Fig. 2, the end of the lever 233 is in alignment with the end 239 of the hook 240. When either detent 236 or 235 drops into the recess 238, the corresponding lever 234 or 233 moves out of alignment with the end 239 of the hook 240. When that happens, both

of the detents are located in the recess 238 and the hook 240 is free to swing to the left, as viewed in Figs. 6, 7 and 8.

It may be noted that the hook 240 is located to the right of the disc 138, and is free to hang downwardly behind this disc as shown in Figs. 6, 7 and 8. The hook 240 is, however, in alignment with the dog 142 carried by the disc 138. When the cam shaft rotates into the position shown in Figs. 2 and 5, the hook 240 engages the dog 142 and raises the detent 143 thereof away from the notched wheel 123, thus terminating the drive of the cams. The hook is enabled to thus actuate the dog 142 owing to the fact that one or the other of the levers 233 or 234 have been moved into alignment with the end 239 of the hook 240. Consequently, when the dog 142 comes into contact with the hook 240, in the position shown in Fig. 2 or Fig. 5, the dog 142 is displaced against the tension of the spring which tends to hold its detent 143 in contact with the notched wheel 133.

When, however, the lever 233 or 234, as the case may be, becomes displaced, at the end of the playing of a record, with respect to the end 239, of the hook 240, then, consequently, that hook becomes free to move to the left as viewed in Figs. 2, 5, 6, 7 or 8, and the dog 142 is thus freed so that it may engage the spur wheel 133. Consequently, the operations of returning the record, moving the magazine to another position, etc., are resumed.

It will be noted that the phonograph will operate automatically and continuously as long as the motor 42 is driven. If any of the bars 32 are pressed inwardly, the corresponding recordings will be played and the corresponding bars will be returned to normal position. If none of the bars 32 are pressed inwardly, or after all the bars have been returned outwardly, the machine functions to play the recordings one after another automatically until the motor 42 is stopped.

The machine is particularly well adapted for coin operation, the coin control mechanism 45 merely controlling the operation of the motor. The coin control mechanism may suitably be mounted on the right-hand side of the frame member 43, being located inwardly of the record playing position. This mechanism is best shown in Fig. 4 and may comprise a coin chute 241, which extends from an upper part of the cabinet and terminates in a suitable cash box (not shown). The coin chute 241 is provided at a suitable point with a slot 242, through which extends a pin 243. The pin 243 is carried by a lever 244 which is pivotally mounted at 245 on the frame member 43. The pin 243 is located in the path of a coin 246 passing down the coin chute 241. The lever 244 is adapted to cooperate with one leaf 247 of a leaf switch 248 so as to bring it into contact with the other leaf 249 when the pin 243 is hit by a falling coin.

The switch 248 is in series with a solenoid 250, and the circuit including the switch 248 and the solenoid 250 is connected to any suitable source of electrical energy (not shown). The armature 251 of the solenoid 250 is connected by means of a slot and pin connection with one end of a lever 252 which is pivotally mounted on the frame member 43. A spring 253 connected to the lever 252 normally moves the armature 251 outwardly with respect to the solenoid 250. This outward movement is limited by a stop 254. Upon one end of the lever 252 is pivotally mounted a dog 255. This dog is normally held in its full

line position, shown in Fig. 4, by means of a spring 256 and abutments 256' on the dog 255 and on the lever 252. Consequently, the dog 255 is free for limited movement in the counter-clockwise direction as viewed in Fig. 4, but is definitely held against movement in the opposite direction. The dog 255 is adapted to cooperate with the tooth on a ratchet wheel 257 which is rotatably mounted on the frame member 43.

The ratchet wheel 257 is biased for movement in the counter-clockwise direction as viewed in Fig. 4 by means of the spring 258. By rotation of the ratchet wheel 257 in this direction is normally prevented by means of the detent 259 of an escapement member 260. This escapement member has a second detent 261 so arranged that when the escapement member 260 is oscillated from its full line position under the influence of the spring 262, the ratchet wheel 257 will rotate one tooth in the counter-clockwise direction.

The ratchet wheel 257 carries a projecting pin 263 which is adapted to cooperate with the arm 264 of the micrometer switch 265. When the pin 263 moves upwardly from its position shown in full lines in Fig. 4 to its position shown in dotted lines it raises the arm 264 from the stop 266 and effects the opening of the switch 265. This switch controls the supply of current to the motor 42 and consequently this movement of the arm 264 terminates the operation of the machine.

The escapement member 260 has pivotally mounted thereon a dog 267 which is held against an abutment 268 on the escapement member 260 by means of a tension spring 269 carried by the dog 267. The dog 267 is adapted to be actuated by a short arm 270 which is rigidly mounted on the shaft 181 upon which are rigidly mounted the record moving arms 89 and 182. When these arms are moved in the clockwise direction, as viewed in Fig. 4, in order to remove a record from the magazine to the turn table elements for playing, the arm 270 merely displaces the dog 267 relative to the escapement member 260 without actuating the escapement member.

When, however, the arms 89 and 183 have reached the final stage of returning the played record to the magazine, the arm 270 rotates the dog 267 in the clockwise direction, as viewed in Fig. 4. This movement carries the escapement member 260 with it owing to the engagement of the dog 267 with the abutment 268. Consequently, the detent 259 is withdrawn from the ratchet wheel 257, but the detent 261 is first interposed in the path of one of the teeth of the ratchet wheel. Consequently, the ratchet wheel is able to rotate in counter-clockwise direction only part of one tooth space. The continued movement of the arms 89 and 183 moves the arm 270 so that the escapement member 260 may resume its full line position as shown in Fig. 4. When this occurs the last part of the one tooth movement of the ratchet wheel 257 is completed. In the event that the pin 263 was in the position shown in full lines in Fig. 4, this last partial movement of the ratchet wheel 257 brings the pin 263 into the dotted line position shown in this figure and effects the opening of the switch 265.

The operation of the phonograph will now be briefly described. A coin 246 is passed down the chute 241, closing the switch 248 and energizing the solenoid 250. Consequently, the dog 255 is moved into its dotted line position in Fig. 4, 75

rotating the ratchet wheel 257 one tooth in clockwise direction. The ratchet wheel 257 is held in that position, which is the position shown in Fig. 4, by the detent 259 on the escapement member 260. If a plurality of coins is inserted in the chute 241, the ratchet wheel 257 is displaced by a corresponding number of teeth. When the first coin is inserted the pin 263 moves away from the switch arm 264 and the switch 10 265 is closed. Consequently, the motor 42 starts operating. This motor operates in one direction or in the reverse direction, depending upon the position of the reversing switch 64. If this switch is snapped in the position shown in full lines 15 in Fig. 15, the motor drives the turn table element 49 in the counter-clockwise direction as viewed in Fig. 2, and consequently the machine will operate to play the right-hand side of a record, as viewed from the front of the machine, 20 that is the side which carries the selector buttons 31. This is the left-hand side of the record as viewed from the rear, as in Fig. 3. It may here be interposed that if the switch 64 were snapped in the opposite direction, the direction of rotation of the turn table member 49 would also be 25 reversed.

When the machine ceases playing the lever 159 is located in the recess 141 of the disc 133 and returns the dog 142 out of engagement with the notched wheel 133. Consequently, the bell crank lever 156 is swung by the spring 158 in such manner that it pushes the pulley 150 inwardly from the position shown in Fig. 16. In that inward position the pins 155 of the pulley 30 are adapted to be operatively engaged by the pin 141 of the sleeve 145, and the pulley 150 is driven in the clockwise direction as viewed in Fig. 2. The screw 55 is therefore driven in counter-clockwise direction, as viewed in Fig. 2, with the result that the magazine moves to the left. During this movement the left-hand dog 82 is operative and the right-hand dog 82 is inoperative, slipping over any of the bars 32 which it may engage.

If any of the bars 32 have been pushed inwardly the rail 77 is elevated as shown in Figs. 12 and 13. Consequently, the dogs 82 are swung round from their position shown in Fig. 10 to their position shown in Figs. 12 and 13. In this 50 relation the dogs 82 avoid contact with the bars 32 which have not been pushed inwardly, but will engage the first bar of the left half series of rods 32 which have been pushed in, as best seen in Figs. 12 and 13.

In Fig. 1 the magazine is shown arrested by engagement of the operative dog 82, that is the left-hand dog, with the inner first rod of the left-hand series, which rod has been pushed inwardly. When the left-hand dog 82 engages this bar 32, the left-hand assembly which includes the left-hand dog 82 and associated sleeves 75 and 70, is arrested and the magazine continues to move until the sleeve 72 abuts against its sleeve 70. The relative movement thus provided between the left and right-hand dogs 82 insures that the left-hand rod return arm 13 is in alignment with the arresting bar 32, whereas, the right-hand return arm 73 is out of alignment with all the bars 32.

70 It may here be noted that if none of the rods was pushed inwardly, the rail 77 would be in the position shown in Figs. 10 and 11, and the left-hand dog 82 would have engaged the next adjacent bar 32, bringing the magazine to a stop in the manner previously described.

When the magazine is thus brought to a stop, the drive of the pulley 150 is overloaded. Consequently, the wedge-shaped formation 144 of the hub of the pinion 134 forces the collar 145 and the ball 154 outwardly, thus swinging the bell crank lever 156 in counter-clockwise direction as viewed in plan. This movement withdraws the lever 159 from the dog 142, so that the latter engages the notched wheel 133 and the cams 139 and 140 start to rotate in the counter-clockwise direction, as viewed in Fig. 2. This rotation removes the notch 141 away from the lever 159, and the latter, owing to its engagement with the periphery of the disc 138, holds the arm 153 in an outward position against the action of the spring 158. Consequently, the sleeve 145 moves to the left when the recess 144 is again presented to its wedge-shaped projection 146, the pins 155 of the pulley 150 being kept away from the pin 147 by the spring 148. This relation persists until the recess 141 is again brought into cooperative relation with the lever 159, after the record has been played and returned to the magazine. When the recess 141 does arrive at its position, shown in Figs. 6 and 7, the pulley 150 moves inwardly again, ready to resume the translation of the magazine.

If the machine last played the right-hand side of a record, the player arm will be left in initial position for the playing of the right-hand side of a record, as is shown in Fig. 2. The reason for this is that two pins 228 and 229 are provided for locating the player arm. Two such pins are provided because the disc carrying these pins may start moving in one direction or the other direction. The result is that the player arm may be thrust to initial position by one pin during the first half rotation of the cam shaft, and is returned to the same initial position during the second half rotation of the cam shaft. For the same reason, the player arm will be located at initial playing position for a left-hand recording, if a left-hand recording was last played.

The cams 139 and 140 are initially in the positions shown in Figs. 6 and 7. When they start moving in counter-clockwise direction, the pin 228 engages the lower end of the lever 225, throwing it clockwise. The lever 225 engages the arm 222 of the sector 198 and throws the sector counter-clockwise, thus rotating the pinion 238 clockwise, as viewed in Fig. 7.

The shaft 192 on which the pinion 195 is mounted and also the bevel gear splined to the shaft rotate in similar direction. If the player arm is merely being moved back to initial playing on the same side it played before, the sector 198 does not need to be displaced very much, and in this case the gears 193 and 200 are not moved relative to the bracket 191 and the player arm assembly generally.

When, however, the player arm 185 is changing over to play the right-hand side of a record when it last played a left-hand side record, then the player arm has to be transported from its position in Fig. 5 to its position in Fig. 2 and it must be rotated about the axis provided by the sleeve 202. For this purpose the sector is thrown through a very wide angle, that is, from its position shown in Fig. 5 to its position shown in Fig. 2. In the initial part of this movement the point of the pin 217 enters the recess 221 in the surface of the bracket 191, this movement occurring when the arm 169 is in the position shown in Fig. 21.

When the sector 198 is moved downwardly, the

movement of the bracket is resisted by the pin 217 in the recess 221, the downward movement of the sector rotates the gear 193 in clockwise direction as viewed in Fig. 5, and the gear 200 is rotated in counter-clockwise direction, as viewed from the left in Fig. 20. Consequently, the player arm is rotated around the axis provided by the sleeve 202 from the left-hand side of the record playing position to the right-hand side thereof, as shown in Figs. 20 and 21.

When the pin 205 reaches the end of the slot 206 in the sleeve 202, further rotation of the gears 193 and 200 is rendered impossible. Thereupon, the force supplied by the sector 198 on the pinion 195 rotates the bracket 191 so as to move the pin 217 out of the recess 221 and bring the player arm to initial playing position for the right-hand side of the record, as shown in Fig. 2.

When about to play a recording on the left-hand side of a record after playing a recording on the right-hand side of a record, the procedure is exactly opposite. In both cases, however, the player arm turns in the same arc which extends upwardly around the position occupied by the upper edge of a record on the turntable. It is to be noted that the levers 233 and 234 operate automatically. Thus, when the player arm 185 is in the full line position shown in Fig. 5, the detent 235 is in the recess 238, while the detent 236 is riding on the periphery of the member 190.

When, however, the player arm moves into the dotted line position shown in Fig. 5, which corresponds to the end of the playing of a recording on the left-hand side of a record, the detent 236 drops into the recess 238 with the results, previously described, of starting movement of the cams 139 and 140 from their position shown in Fig. 5, to their position shown in Fig. 6.

When the player arm is reversed from its position as shown in Fig. 5 and is carried downwardly, in the manner previously described, the detent 236 remains in the recess 238 and likewise does the detent 235 until the position of the end of playing of a right-hand recording is reached. Thereupon the detent 235 rises out of the recess 238 and below that point this detent rides on the surface of the member 190.

It merely remains to draw attention to the coordination of the cam actuated members which effect the movements of the record from and to the magazine, the means for controlling the movable turntable element and its centering pin and the means for moving the needle away from the record.

The cams 139 and 140 are initially in the position shown in Fig. 6. It is to be noted that these cams are symmetrical with respect to the elements which engage them. Consequently it does not matter, as far as the mechanisms just mentioned are concerned, whether the cams rotate in one direction or the other. It is to be noted that the three-armed member 164, 167, and 172 is rotated to its greatest extent in the clockwise direction. Consequently, the turntable element 49 and its centering pin 121 are retracted in the manner shown in Fig. 19 and consequently the needle is raised away from the record position and this is true irrespective of the position of the needle on one side or on the other side of the record playing position.

The lever 175 is on the lowest point of the cam 139 and consequently the levers 89 and 183 have the positions shown in Fig. 6. When the cams 139 and 140 start moving from the posi-

tion shown in Fig. 6, the arms 88 and 183 start swinging to the left as viewed in that figure.

The swinging of the player arm 185, by the pin 228 or 229, if that is necessary, is effected as the record is moving out of the magazine.

After the record is fully removed from the magazine, that is after it rolls over the bar 46 which is next the record playing position, and drops on to the arm 183, the roller 173 of the arm 172 moves over a fall on the cam 140, so that the three arms are permitted to rotate in counterclockwise direction as viewed in Fig. 2. Consequently, the arm 124 moves inwardly, first projecting the pointed end 125 of the center pin 121 through the central opening in the record, thereby raising the record from the bar 46 and from the bar 183, and thus moving the turn table member 49 inwardly so as to clutch the record between the turn table members 49 and 50. At the same time the downward movement of the arm 167 allows the arm 169 to move outwardly away from the shaft 192. Consequently, the spring 196 moves the shaft 192 from the position shown in Fig. 21 to the position shown in Fig. 20. When that movement is effected, the spring 210a moves the player arm towards the record so as to apply the needle thereto with sufficient resilience to enable it to properly cooperate with the sound groove on the record.

When these movements have been completed 30 the cams 139 and 140 are in the position shown in Figs. 5 and 2. At this time one of the levers 233 or 234 is located opposite the end 239 of the hook member 240. This hook member is engaged by the tail of the dog 142 and is swung against said lever which serves as an abutment for the hook 240 which acts to elevate the detent 143 out of engagement with the spur wheel 133. The cams 139 and 140 are now arrested and they remain in that condition until the recording has 40 been played.

When the playing of the record is completed the lever 233 or 234, as the case may be, clears the end 239 of the hook member 240. The dog 142 is released and the cams begin rotation and return to the position shown in Figs. 6 and 7. During this semi-rotation the reverse movements occur, that is, the shaft 192 moves inwardly and raises the needle from the record. The turn-table element 49 is retracted, likewise the centering pin 121, and the played record is allowed to descend on to the arm 183. The arm 183 then returns the played record to the magazine.

When the arm 89 approaches its initial position, that is, its position shown in dotted lines Fig. 2, the projection 88 at the end thereof engages the bar 68 and allows the effective dog 82 to move to some extent past the bar 32 which arrested it, thus enabling the magazine to resume its movement during the next cycle. Also 60 at the end of the operation of returning the played record to the magazine, the escapement member 260 is oscillated in the manner previously described. If the pin 263 occupied the position shown in Fig. 4 during the playing of the record, this pin is now moved to its dotted line position in Fig. 4, and the switch 265 is opened and the motor 42 stops.

If, however, a plurality of coins had been originally inserted, the pin 263 will occupy a position displaced from its full line position in Fig. 4 in the clockwise direction. If this is the case, then the ratchet wheel 257 will merely rotate the distance of one tooth without affecting the switch 265. Consequently, the motor 42 will keep run- 75

ning and the cycle will be repeated with successive records until eventually the pin 263 is moved to its dotted line position in Fig. 4 and the switch 265 is opened. It will readily be understood from the earlier description that the successive records thus played are thus corresponding to the bars 32 which have been pressed inwardly, if any. If none of the bars 32 has been pressed inwardly, the machine will play the same sides of successive records in the manner hereinbefore indicated.

The selector mechanism illustrated in Figs. 23 to 29, inclusive, may be used instead of that described in connection with Figs. 9 to 13, inclusive. The two selectors comprise many similar elements which are designated by the same reference numerals as have been employed in the previously described embodiment.

The magazine 39 carries a shaft 67 upon which is pivotally mounted a bail 68 which is normally maintained in the position shown in Fig. 24 by means of springs 91. The ends of the bail 68 are separated from the end walls 45 of the magazine by means of washers 69. On the inner side of each end of the bail 68 and slidably mounted on the shaft 67 is a sleeve 70. These sleeves are pressed away from each other by means of a spring 74 so that their remote ends always tend to abut against the ends of the bail 68. The sleeves 70 may be caused to approach each other to a slight extent, the degree of approach being controlled by the spacing sleeve 72, around which the spring 74 is mounted. Adjacent its outermost ends, each sleeve 70 rigidly carries an arm 73 to which is connected a spring 371 which is connected to the magazine and which tends to rotate the sleeve 70 in the clockwise direction, as viewed in Fig. 24. The arm 73 is provided with a shoulder 372 which is adapted to be engaged by the bail 68, when that bail is thrown by the projection 88 on the lever 89 in the counter-clockwise direction, as shown in Fig. 25. This occurs when a record has been returned to the magazine. The arm 73 also carries a shoulder 373 which is adapted to engage one of the detents 374, which will be more fully described. It may, however, be noted that this engagement effects the movement of the detent 374 from its position shown in Fig. 24 into its position shown in Fig. 25.

50 The sleeve 70 carries a lateral extension 375 on which is rigidly carried a dog 376. Also mounted on this lateral extension is a pivoted dog 377. The dogs 376 and 377 are suitably located together and the latter is pressed downwardly by means of a spring 378 so that it tends to occupy a lower position than does the dog 376.

The lateral extension 375 is also provided with an abutment 76 which may suitably be an extension of the pivot of the dog 377. The abutment 76 is adapted to cooperate with a bar 71. This bar is pivotally mounted by means of end members 78 upon brackets 80 carried on the frame 36. Through these brackets extends a shaft 79. The shaft 79 has mounted thereon a series of discs 379 corresponding in number to the number of selections or recordings for which the machine is intended. That number is, of course, double the number of the records for which the magazine is intended. Each disc 379 is rotatably mounted on a spacing washer 380 which is supported on the shaft 79. Between adjacent discs 379 and spacing washers 380 are located discs 381 which effectively space the discs 379, corresponding to the spacing of the records in the magazine. The spacing washers 380 are

slightly wider than the discs 379 so that these discs are free to rotate to a certain extent into the two positions shown in Figs. 24 and 25. The discs 379 and 381 have the same diameter so that they are in substantial alignment, as best seen in Figs. 27 and 28. Each disc 379 carries one of the detents 374, previously referred to, and also a radial arm 382, the detents 374 and arm 382 projecting radially beyond the discs 381. The outer edges of the discs 381 are beveled, as shown in Figs. 23, 27 and 28. The center disc 381 of the series of discs is beveled towards both sides. The other discs 381 are beveled on the side farthest away from the center disc, as best seen in Figs. 27 and 28. Each disc 379 is provided with a peripheral recess 383. This recess is so located that it is adapted to receive the dog 377 when it is in the position shown in Fig. 24 and is out of alignment with the dog 377 but in alignment with the dog 376, when the disc 379 is in the position shown in Fig. 26. It may be noted that these two positions of the discs 379 are defined by two peripheral recesses 386 which are adapted to be engaged by a resilient member 397. The resilient detent member 397 may suitably be part of a comb-like member 398 which extends along the series of discs 379.

The frame 36 supports a cylinder 384 beneath each of the arms 382. The cylinders 384 are staggered in the longitudinal direction of the series of arms 382 for the sake of greater clearance. Within the cylinder 384 is slidably mounted a plunger 385 which is connected to a cable 386. The sheath 387 of the cable 386 may be connected to the cylinder 384. This sheath may also be connected to a cylinder 388 which may be rigidly carried by a panel 389, which may suitably be mounted on a wall 30 of the cabinet. The cables 386 are connected by short bars 390 to buttons 391, which may suitably project through suitable openings in a small housing 392 mounted on the panel 389. Each button 391 may be associated with a strip 393 which may bear the title of the selection corresponding to the associated button. It will readily be understood that when one of the buttons 391 is pressed inwardly from its position shown in Fig. 29, the corresponding cable 386 will be moved inwardly and the corresponding cylinder 385 will be projected upwardly. The plunger 385 is in engagement with the arm 382 of the associated disc 379, and consequently, this disc will be rotated from the position shown in Figs. 25 and 26 into the position shown in Fig. 24. When one or more of the discs 379 is displaced in this manner, the bar 71 is elevated into its position shown in Fig. 24. The elevation of the bar 71 throws the two sleeves 70 from the position shown in Fig. 26 into the position shown in Fig. 24. This movement elevates the dogs 376 which are rigidly carried by the sleeves 70 out of contact with the stop discs 381. The dogs 377 are pressed downwardly by the springs 378 towards the edges of the discs 379 and 381. Each of the dogs 377 has a relatively large nose 394, as best seen in Fig. 27. This nose is of such length that it cannot enter the space 395 provided between the beveled surface of one of the discs 381 and the adjacent disc 379. When, however, the disc 379 is displaced into the position shown in Fig. 24, so as to bring the recess 383 into alignment with the dog 377, the nose 394 of that dog is able to enter between two adjacent discs 381 so that the carriage is arrested by the engagement of the dog 377 with the square or 75

unbeveled edge of one of the discs 381. This condition is shown in Fig. 27.

Consequently, when one or more of the buttons 391 have been pressed inwardly, the dog 376 is rendered inoperative and the dog 377 is arrested only by a disc 381 adjacent a disc 379 which has been actuated by one of the buttons 391. It will be understood that only one of the two dogs 377 is effective at any time. Thus, referring to Fig. 23, the magazine is arranged to move downwardly in that figure. During this movement, the upper dog 377 merely slips over the discs 379 and 381. When, however, the direction of movement is reversed, the lower dog 377 becomes ineffective and the upper dog 377 becomes effective, that is, it is adapted to be arrested by any of the upper series of buttons 391 with which it is permitted to make arresting contact owing to the actuation of the associated disc 379 to bring its recess 383 into alignment with the dog 377. It will be understood that when the dog 377, for example, the lower dog of Fig. 23, arrests the magazine as in Fig. 24, the arresting sleeve 70 will move axially toward the other sleeve 70 upon the shaft 67 and the arm 73 carried by the arresting sleeve 70 is located in alignment with the actuated or displaced disc 379 which permitted the dog 377 to make engagement with the adjacent stopping disc 381. The movement of the magazine and the other sleeve 70 after the arrestment of the arresting sleeve 70 is sufficient to locate the arm 73 associated with said other sleeve 70 out of alignment with any of the discs 379. This displacement of the last named arm 73 is equivalent to the space between the lower sleeve 70 in Fig. 23 and the adjacent end of the bail 68.

When the record being played is returned to the magazine, the projection 88 on the arm 89 strikes the bail 68 and swings it in the manner shown in Fig. 25. The engagement of the bail 68 with the shoulder 372 of the arm 73 brings the shoulder 373 of this arm into contact with the projection 374 of the disc 379 which caused the arrestment of the magazine. This disc is thereby returned to its initial position, as shown in Fig. 25, and the plunger 385 is pressed downwardly so that the associated button 391 is returned to initial position. As in the previously described embodiment of the invention, the carriage now moves forwardly again, and the cycle is repeated until all of the buttons 391 which have been pressed inwardly have been discharged. When that occurs, the bar 71 moves downwardly and the subsequent operation occurs automatically, one side of one record being played and the same side of the next record, and so on until the magazine has completed its travel. At the completion of this travel, the magazine reverses and the other sides of the records are played in series, until eventually the main switch opens and playing ceases.

When no button 391 has been pushed inwardly, the discs 379 and dogs 376 and 377 have the relation shown in Fig. 26. The dogs 377 are rendered inoperative because all of the slots 383 are out of alignment with them. Owing to the low position of the bar 71, the dogs 377 are pressed upwardly against the action of their springs 378 by the superior tension of the springs 371. Thus the dogs 376 are in operative condition. Thus, referring to Fig. 28, it will be seen that all of the slots 383 are in alignment with the dogs 376, and consequently the stop discs 381 are all operative. When the arm 89 swings the dogs clear of the discs 379 and 381, the spring

74 moves the effective arresting sleeve 78 outwardly and when the dogs move downwardly again, the dog 376 is no longer in arresting relation with the same disc 381. Consequently, the motor drives the magazine to bring the dog 376 into engagement with the next arresting disc 381. This cycle continues indefinitely until the main switch opens or until one of the buttons 391 is pressed inwardly. It will of course be understood that the nose of the dog 376 is substantially similar to the nose 394 of the dog 377.

The embodiment of the invention disclosed in Figs. 31 to 36, inclusive, differs primarily from the previously described embodiments in that two player arms 400 and 401 are provided on opposite sides of the record 118 in record playing position. These player arms are provided with pickups 402 and 403, respectively. The player arm 400 is pivotally mounted on a pair of arms 404 and the player arm 401 is pivotally mounted on a pair of arms 405. The pairs of arms 404 and 405 extend in radial direction from bosses 406 and 407, respectively. The bosses 406 and 407 project radially and in angular relation from a bracket 191 which is analogous to the bracket of the same number in a previously described embodiment. It may be noted that the angular relation between the two player arms 400 and 401, provided by the angular relation of the bosses 406 and 407, is preferably such that when one of the player arms is approximately in its initial playing position, the other player arm will be substantially in its final playing position relative to the record. It is to be noted in this connection, however, that at no time are the needles of the two tone arms in contact with the record at any one time. This relation between the player arms is best seen in Fig. 31.

The bracket 191 carries a counterpoise weight 185, as in the previously described embodiment, and it is rigidly connected to a sleeve 188 which is rotatably mounted in a bearing 186 carried by the frame member 43. The sleeve 188 has mounted thereon the pinion 195 which meshes with the sector 198 in the same manner as in the previously described embodiment. The sleeve 188 also carries the collar 190 which cooperates with the two levers 233 and 234 to initiate the record changing at the end of the playing of a selection.

The bosses 406 and 407, respectively, are provided with axial pins 408 and 409, respectively. These pins are adapted to cooperate with the cam member 410, which will hereinafter be more fully described. The pins 408 and 409 abut against projections 411 and 412, respectively, which are rigidly connected to the player arms 400 and 401, respectively. The projections 411 and 412 are analogous to the projection 210 of the player arm 185 in the previously described embodiment. It will be understood that when the pin 408 or 409 is forced radially outwards, the corresponding player arms are moved away from the record, that is, the needle is moved out of contact with the record. The player arms 400 and 401 are biased towards the record in playing position by means of springs 431.

The shaft 192 which extends through the sleeve 188 rigidly carries the cam member 410 which is located within the bracket 191. The shaft 192 is forced downwardly, as viewed in Fig. 32, by means of a spring 196 which abuts against a collar 197 carried by the shaft, and against the pinion 195 which is splined to the shaft. It is to

be noted, however, that the shaft 192 is free to move relatively to the bracket 191. There is, however, a substantial degree of friction between the shaft 192 and the sleeve 188 so that the bracket 191, together with the player arms, tends to move whenever the sector 198 throws the shaft 192 in one direction or the other.

The player arm system, that is, the bracket 191 and the associated player arms 400 and 401, is free to move to the two positions shown in Fig. 31. These extreme positions are defined by a stop member 414 which is integral with the bracket 191 and the two stop screws 415 (see Fig. 34). These screws have eccentric heads so that they may be rotated through the proper angle to adjust the stop to the precise position required. The screws 415 may suitably be mounted on suitable bosses carried by the frame member 43. The cam member 410, which is rigidly mounted on the shaft 192, is of generally cylindrical form. When one or both of the pins 408 and 409 are in contact with the cylindrical surface of the cam member 410, as is the case with the pin 408, as shown in Fig. 34, the corresponding projection 411 or 412 is forced outwardly and the tone arm is thus moved away from the record; that is, its needle is withdrawn out of contact with the record 118. When both the pins 406 and 408 are in contact with the cylindrical surface of the cam member 410, a record may be moved into record playing position or withdrawn therefrom without danger of being scratched by either or both of the needles of the pickups 402 and 403.

35 The end of the cam member 410, which is remote from the bearing 186, is provided with a short groove 416 which tapers upwardly and terminates approximately in the center of the cylindrical cam member 410, as best seen in Figs. 33 and 35. During the normal playing of a selection, the needle of one or the other of the pickups 402 or 403 is in contact with the record. The corresponding pin 408 or 409 is located within the deeper end of the groove 416 so as to enable the corresponding needle to engage the adjacent side of the record. As shown in Figs. 31 to 35, inclusive, the pin 409 is located within the groove 416 and the player arm 401 is biased by its spring 431 towards the adjacent face of the record, as viewed in Fig. 31, or the lower face of the record, as viewed in Fig. 32. During the playing operation, the tone arm assembly moves downwardly from its full line position as shown in Fig. 31 towards its dot and dash position shown in that figure. This continues until the lever 234 drops into the recess 238. During the downward travel of the player arm assembly, the pin 409 carries the cam member 410 and the shaft 192 with it. When the detent 236 of the lever 234 drops into the recess 238, the rotation of the cam shaft for approximately one-half revolution is initiated in the manner previously described. As a result of the rotation of the cam shaft, the arm 169 is moved upwardly, as viewed in Fig. 32, so that the shaft 192 and cam member 410 are moved in the same direction. The immediate result of this movement is the movement of the needle of the pickup 403 away from the record 118. It is to be noted that the needle of the pickup 402 was out of contact with the record. During the continued rotation of the cam shaft, the record is returned to the magazine and the tone arm assembly is moved upwardly by the sector 198 to the initial playing position for the pickup 403, and the cam shaft is then arrested. The

magazine then moves to bring the next record to be played into position, and the cam shaft again starts operating to effect the transfer of the record to the playing position.

It will be noted that when the sector 198 throws the player arm assembly, this movement is effected by the shaft 192. This shaft has a frictional connection with the sleeve 188 and the bracket 191 so that the initial part of the movement effected by the sector 198 carries the tone arm assembly until the projection 414 engages the appropriate stop 415. The final movement of the sector 198 in all cases leaves the groove 416 in alignment with the appropriate pin 408 or 409, so that when the arm 169 moves downwardly, as viewed in Fig. 32, the appropriate pin 409, for example, drops into the groove 416 and consequently brings the pickup 403 into playing relation with the appropriate side of the record.

When the magazine comes to the end of its movement in one direction and the direction of the motor is reversed, then when the next record is being transferred to record playing position, the tone arm assembly is thrown from one extreme position to the other. That is, during the record returning part of the cycle, assuming that the near face of the record 118, as shown in Fig. 31, has been played, the pickup 403 is returned to its position as shown in Fig. 31. Now, if the direction of the motor is reversed, then during the transfer of the next record to record playing position, the tone arm assembly is swung downwardly so as to bring the pickup 402 downwardly to its dash and dotted position shown in Fig. 31. This same movement, which is effected by the sector 198, is terminated by the stops 414 and 415. However, the movement of the sector 198 is sufficient to carry the groove 416 out of alignment with the pin 409 and into alignment with the pin 408. Consequently, when the arm 169 moves outwardly and allows the shaft 192 to move under the influence of the spring 196, the groove 416 is located in alignment with the pin 408 so that the needle of the pickup 402 moves into contact with the record 118, whereas the needle of the pickup 403 remains out of contact with the record. The two pickups 402 and 403 are preferably connected in series, as shown in Fig. 36, and a single pole, double throw switch 417 is adapted to short circuit one or the other. Thus, as shown in Fig. 34, the switch 417 may comprise a pole 418 which is adapted to make contact with either of two contacts 419 and 420. The pole 418 carries a member 421 which is adapted to bear against the cam member 410, as shown in Fig. 34. This cam member has a flat side 422 which is adapted to be engaged by the member 421 when the groove 416 is in alignment with the pin 409. In this relation the pole 418 is in engagement with the contact 420. Consequently, as will be best understood from Fig. 36, the pickup 402 is short circuited and consequently, only the pickup 403 is effectively connected to the pickup leads 423. These leads are connected to an amplifying and loud speaker system (not shown) in known or other suitable manner.

When the cam member 410 is moved so as to bring the groove 416 into alignment with the pin 408, which occurs when the pickup 402 is to be brought into operation, the member 421 is displaced downwardly, as viewed in Fig. 34, the pole 418 is moved out of engagement with the contact 420 and is brought into engagement with the contact 419. In this relation, it will readily be seen that the pickup 403 is short circuited and that

the pickup 402 is effectively connected to the amplifying and loud speaker system.

Although the invention has been described in connection with the specific details of preferred embodiments thereof, it must be understood that such details are not intended to be limitative of the invention, except insofar as set forth in the accompanying claims.

Having thus described my invention, I declare that what I intend to claim is:

1. In a phonograph, in combination, means for rotating a disc record in a fixed playing position, reproducing means adapted to be brought into cooperative relation on either side of said position with a record in said position, a magazine containing a series of records in face to face relation, means for moving said magazine in either one of two directions to bring a record therein into substantial alignment with said playing position, means for transferring the aligned record from said magazine to said rotating means and back to said magazine after playing, and means operatively connected to the magazine moving means for causing said reproducing means to cooperate with one side of the record in said position when said magazine moves in one direction and to cooperate with the other side of the record in said position when the magazine moves in the opposite direction.

2. In a phonograph, in combination, means for rotating a disc record in a playing position, reproducing means adapted to be brought into cooperative relation on either side of said position with a record in said position, a magazine containing a series of records in face to face relation, means for effecting relative movement between the magazine and the means defining the playing position in either of two opposite directions to effect substantial alignment between any record in said magazine and said playing position, means for transferring the aligned record from said magazine to said rotatable record supporting means and back to said magazine after playing, and means controlled by said movement effecting means for causing said reproducing means to cooperate on one side of said position with one side of the record in said position when the relative movement is in one direction and to cooperate on the other side of said position with the other side of the record in said position when the relative movement is in the opposite direction.

3. In an automatic phonograph, a magazine adapted to support a plurality of records, turntable means defining a record playing position, reproducer means adapted to cooperate on either side of said position with a record in said position, means for moving said magazine progressively in one direction or progressively in the opposite direction to any of a plurality of definite positions in which a definite record is in alignment with said playing position, means for transferring said aligned record between the magazine and said turntable means, and means for causing said reproducer means to contact and play a record on one side of the playing position and to cause the magazine to move in a corresponding direction, and for causing said reproducer means to contact and play a record on the other side of the playing position and to cause the magazine to move in the opposite direction.

4. In an automatic phonograph, a magazine adapted to support a plurality of records, turntable means defining a record playing position, reproducing means adapted to cooperate with a

record in said position, means for moving said magazine progressively in one direction or progressively in the opposite direction to any of a plurality of definite positions in which a definite record is in alignment with said playing position, means for transferring said aligned record between the magazine and said turntable means, means causing said reproducer means to contact and play a record on one side of said playing position, and causing the magazine to travel in a corresponding direction and causing the turntable means to rotate in the direction corresponding to the side of the record engaged by said reproducer means.

5. In an automatic phonograph, a magazine adapted to support a plurality of records, turntable means defining a playing position, reproducer means adapted to contact and play on either side of said position a record in said position, means for effecting relative movement between said magazine and said turntable means in one direction or in the opposite direction for bringing any of said records into alignment with said playing position, means for transferring said aligned record between the magazine and said turntable means, means for reversing the direction of said relative movement, and means controlled by said reversing means for locating said reproducer means on one side or the other side of the playing position.

6. In an automatic phonograph, a magazine adapted to support a plurality of records, turntable means defining a record playing position, a player arm adapted to be moved from one side of the record playing position to the other to cooperate with either side of a record in said position, means for driving said magazine in one direction or in the opposite direction for bringing any of said records into alignment with said playing position, means for transferring said aligned record between the magazine and said turntable means, means for reversing the direction of said driving means, and means controlled by said reversing means for moving said player arm from one side of the playing position to the other.

7. In a phonograph, in combination, turntable means defining a playing position, a magazine adapted to support a plurality of records, means for driving said magazine in opposite directions past said turntable means to bring said records into alignment with said playing position, a plurality of stops adapted to arrest said magazine, a pair of arresting elements on the magazine adapted to engage said stops with a record in alignment with said playing position, one of said arresting elements being arranged to stop the movement of the magazine in one direction and the other being arranged to arrest the movement of the magazine in the opposite direction, and means associated with each arresting element for returning said stops to initial position.

8. In an automatic phonograph, in combination, a magazine adapted to support a plurality of records, turntable means defining a record playing position, sound reproducing means adapted to cooperate with a record in said position, means for causing said sound reproducing means to contact a record in said playing position on one side and on the other side of said playing position, means for moving said magazine progressively in one direction through a range of movement and progressively in the opposite direction through said range to any of a plurality of definite positions in which a definite

record is in substantial alignment with said playing position, automatic means for reversing the direction of said moving means at each end of said range, and means for transferring said aligned record from the magazine to the turntable for playing, and back to the magazine after playing.

9. In an automatic phonograph, in combination, a magazine adapted to support a plurality of records, turntable means defining a record playing position, reproducing means adapted to cooperate with a record in said position, means for moving said magazine step by step in one direction and means for moving said magazine

10 15 step by step in the opposite direction to definite positions in which definite records are individually located in alignment with said playing position, means associated with said moving means to cause the sound reproducing means to engage 20 a record in playing position selectively on one side or the opposite side of said position, and means for transferring an aligned record from said magazine to the turntable for playing and back to the magazine after playing.

15 25 10. In an automatic phonograph, in combination, a movable magazine having a plurality of spaces for a corresponding number of records, means for moving the magazine in opposite directions, arresting means carried by the magazine and movable in opposite directions therewith, actuatable stops adapted when actuated directly to contact said arresting means to stop the magazine, said stops corresponding in number to twice the number of records, each stop

30 35 40 45 corresponding to the recording on one side of a record, said arresting means and an actuated stop being correlated to arrest the magazine with the selected record in a definite position, certain of said stops being adapted to cooperate with said arresting means when the magazine travels in one direction and the other stop being adapted to cooperate with said arresting means when the magazine travels in the opposite direction, and means for reproducing the recording corresponding to an actuated stop.

11. In an automatic phonograph, in combination, a movable magazine having a plurality of spaces for a corresponding number of records, means for moving the magazine in opposite directions, stops corresponding in number to twice the number of records, each stop corresponding to the recording on one side of a record, and a pair of arresting members on said magazine; one of said arresting members being adapted to engage the stops corresponding to the recordings on one side of said records when the magazine moves in one direction and the other engaging member being adapted to engage the arresting members corresponding to the recordings on the opposite side of said records when the magazine moves in the opposite direction.

12. In a phonograph, in combination, means for rotating a record in a definite playing position, means for reversing the direction of rotation of said means, reproducing means adapted to contact and play a record on either side of said playing position, a magazine adapted to contain a series of records in face to face relation, means for moving said magazine in either direction, means for transferring a record from said magazine into said playing position, and means associated with the magazine moving means for causing said reproducing means to contact and play one side of a record in said playing position when said magazine moves in

one direction, and to contact and play the other side of a record in said position when the magazine moves in the opposite direction.

13. In an automatic phonograph, in combination, a magazine adapted to accommodate a plurality of disc records in vertical face to face relation, a record support for rotating a record in a definite vertical playing plane substantially parallel to the plane of a record in said magazine, means for driving said support in either direction, means for causing relative motion between said magazine and said support in opposite directions to bring the plane of any record in said magazine substantially into alignment with said playing plane, means for transferring a record from said magazine to said record support by horizontal, edgewise rolling movement substantially in said playing plane, reproducing means adapted to engage and play said record on both sides of said playing plane, and means controlled by said motion causing means for causing said reproducing means to cooperate on one side of said position with one side of the record in said position when the relative movement is in one direction and to cooperate on the other side of said position with the other side of said record in said position when the relative movement is in the opposite direction.

14. In a phonograph, in combination, turntable means defining a playing position, a magazine adapted to support a plurality of records, means for driving said magazine in opposite directions past said turntable means to bring said records into alignment with said playing position, a plurality of stops adapted to arrest said magazine, a pair of arresting elements movable with the magazine adapted to engage said stops with a record in alignment with said playing position, one of said arresting elements being arranged to stop the movement of the magazine in one direction and the other being arranged to arrest the movement of the magazine in the opposite direction, means associated with each arresting element for returning said stops to initial position, and means providing a limited movement of the effective arresting element relative to the magazine whereby the return means associated with the ineffective stop element is moved out of alignment with all of said stops.

15. In an automatic phonograph, in combination, a cabinet, turntable means adapted to receive a record in playing position, means for rotating said turntable means, reproducing means and means for transferring records to said turntable means located within said cabinet, a magazine in said cabinet, means adapted to produce relative motion in opposite directions between said magazine and said turntable means, said magazine carrying a plurality of records in parallel relation to said playing position, stops stationary with respect to said cabinet corresponding to each side of each record in said magazine adapted to be selectively actuated, stop engaging means movable in opposite directions with the movable element of said relatively movable elements to arrest said relative movement with the record corresponding to an actuated stop in substantial alignment with said record transfer means and said turntable means so that transfer from said magazine to said turntable and rotation thereon may be effected in a single plane, the actuation of one of said stops corresponding to one side of a record in said magazine being adapted to arrest relative movement 75

between said turntable means and said magazine in one direction and the actuation of the other of said stops corresponding to the other side of said record being adapted to arrest said relative motion in the opposite direction.

16. In an automatic phonograph, in combination, rotatable means for supporting a record in playing position with the recording grooves on each side exposed, power means for rotating said supporting means in either direction, a single player arm, means for moving said player arm into contact with a side of a record on one side of said playing position or on the other side of said playing position, according to the direction of rotation of said rotatable means, a magazine, power means for moving said magazine past said playing position, and power means for transferring records between the magazine and playing position in the plane of said playing position.

17. In an automatic phonograph, in combination, a movable magazine having a plurality of spaces for a corresponding number of records, means for moving the magazine, members corresponding to the records of the magazine for arresting said magazine with a certain record in position to be played, said members being adapted to be manually displaced into arresting relation, and means movable with the magazine for engaging each arresting member to stop the magazine with each record therein successively in position to be played when none of the arresting members have been manually displaced.

18. In an automatic phonograph, in combination, a magazine, turntable means, means for transferring a record between said magazine and said turntable means, means for rotating said turntable means in either direction to adapt the record for playing on either side, a cam driven by said rotating means, a member actuated by said cam for operating said transferring means, said cam being symmetrical with respect to the member engaging it whereby the transferring operation is similarly effected with either direction of rotation of said rotating means.

19. In an automatic phonograph, in combination, a magazine, means for rotatably supporting a record in playing position with the recording grooves on each side exposed, drive means for rotating said supporting means in either direction, reproducing means, rotating means adapted to be driven by said drive means in either direction, means actuated by said rotating means when operated in either direction for transferring records between the magazine and said playing position, and means associated with said rotating means for locating said reproducing means in initial playing position on one side or the other of the record playing position depending upon the direction of rotation of said drive means.

20. In an automatic phonograph, in combination, means for rotatably supporting a record in playing position with the recording grooves on each side exposed, means for supporting a plurality of records in a storage position, means to cause a record to be moved from said storage position into said playing position, means for rotating the first said means in either direction, reproducing means, and means driven by the rotating means in one direction or the other for selectively bringing said reproducing means into initial playing relation on either side of the

record playing position defined by said record supporting means.

21. In an automatic phonograph, in combination, means for rotatably supporting a record in playing position with the recording grooves on each side exposed, a reversible electric motor for rotating said supporting means in either direction, a pair of reproducing means positioned permanently one each on each side of said playing position, and means actuated by the motor when operating in one direction for bringing said reproducing means into initial playing relation on one side of the record playing position defined by said record supporting means, and actuated by the motor when operating in the other direction for bringing said reproducing means into initial playing relation on the other side of said record playing position.

22. In an automatic phonograph, in combination, means for rotatably supporting a record in playing position with the recording grooves on each side exposed, drive means for rotating said supporting means selectively in either direction, means for supporting a plurality of records in a storage position, means to cause a record to be moved from one of said positions to the other of said positions, reproducing means, and means controlled by said drive means for bringing said reproducing means into initial playing position on either side of said record playing position in accordance with the direction of rotation of said record supporting means.

23. In an automatic phonograph, in combination, a travelling member, a stop member thereon, a plurality of elements corresponding to a series of positions of arrestment for said travelling member, said stop member and said elements having normal positions whereby the travelling member is successively arrested by said elements at each of said positions, said elements being capable of individual manual actuation, means operably associated with said elements for displacing said stop member, when any one of the elements is actuated, whereby said stop member is moved out of alignment with said elements in unactuated position and is brought into alignment with the elements which have been actuated, whereby said travelling member is adapted to engage and be arrested by the actuated elements.

24. In an automatic phonograph, in combination, a record magazine accommodating a series of records, turntable means for rotating a record in playing position, means for causing relative motion in opposite directions between said magazine and said turntable means, a series of displaceable stops, each corresponding to a record position in said magazine, stop engaging means movable with the movable one of said relatively movable elements relative to said stops in opposite directions and to engage a stop to arrest said relative motion with the corresponding record position in substantial alignment with said playing position, said engaging means being adapted to engage certain of said stops when displaced and when said relative motion is in one direction and to engage others of said stops when displaced and when said relative motion is in the opposite direction.

25. In an automatic phonograph, in combination, a record magazine, means for rotatably supporting a record in playing position with the recording grooves on each side exposed, means for transferring a record from said magazine to

said supporting means, drive means for rotating said supporting means in either direction, reproducing means, tone arm means carrying said reproducing means and moving about an axis perpendicular to the plane of said playing position, means operable by said drive means in one direction or the other for moving said reproducing means about said axis into initial playing position on the side of the record corresponding to one direction of rotation and on the side of the record corresponding to the other direction of rotation.

26. In an automatic phonograph, in combination, turntable means, a magazine adapted to accommodate a series of disc records, rotatable helical screw means for causing relative motion between said magazine and said turntable means through a limited distance and back again to effect substantial alignment between any record in said magazine and said turntable means, power means for driving said turntable means in either direction, means for rotatably driving said screw means from said power means, and means for reversing said power means at each end of the relative travel between said magazine, and said turntable means, thus reversing the turntable means, the screw means, and the direction of said relative motion.

27. In an automatic phonograph, in combination, a magazine accommodating a series of records, turntable means for rotating a record in playing position, an electric motor for causing relative motion between said magazine and said turntable means, a series of displaceable stops, each corresponding to a record position in said magazine, stop engaging means adapted to move relative to said stops and to engage a stop and to be arrested thereby, and means actuated by the arrestment of said engaging means to arrest said relative motion with the record position corresponding to the engaged stop in substantial alignment with said playing position, means for transferring aligned records from said magazine to said turntable means and back to said magazine, switch means for starting and stopping said motor, and means normally locating said stop engaging means to cause it to engage each stop sequentially when no stops are displaced, and means actuated by a displaced stop for locating said stop engaging means clear of the undisplaced stops and into engaging relation with displaced stops.

28. In an automatic phonograph, in combination, a magazine adapted to support a plurality of double-faced disc records, record rotating means adapted to support and rotate a record in a definite playing position, means for driving said second rotating means in either direction, record reproducing means adapted to be brought into cooperative relation on either side of said position to contact and play both sides of said record in said playing position, means for causing relative motion between said magazine and said support, selective means for arresting said relative motion with any desired record in said magazine in cooperative relation with said record rotating means, record transfer means operable to transfer a selected record from said magazine to said rotating means and to return it to said magazine, power means for operating said motion causing means, said record transfer means, said record rotating means, and said record reproducing means to transfer any desired record from said magazine to said record rotating means

to rotate it, to reproduce it, to return it to said magazine, to cause said relative motion so that another record is in cooperative relation with said record rotating means, and to repeat said operation, and means to cause said record reproducing means to play one side of a record when the relative motion between said magazine and said support is in one direction just prior to arrestment by said selective means and for playing the other side of the record when the said relative motion is in the opposite direction just prior to arrestment by said selection means.

29. In an automatic phonograph, in combination, a unit including a record magazine adapted to accommodate a series of records, a unit including turntable means for rotating a record in playing position, means for causing relative motion between said units, a series of apertured stop members on one unit, each corresponding to a record position in said magazine, aperture entering arresting means on the other unit adapted to enter an aperture in an apertured member to arrest said relative motion with a corresponding record position in substantial alignment with said playing position, manually operable means for moving said apertured members individually into operated position to bring their apertures into alignment with said arresting means whereby said arresting member can enter said apertures, and automatic means for moving said apertured members individually into unoperated position with their apertures out of alignment with said arresting means.

30. In an automatic phonograph, in combination, a unit including a record magazine adapted to accommodate a series of records, a unit including turntable means for rotating a record in playing position, means for causing relative motion between said units, a series of apertured stop members on one unit, each corresponding to a record position in said magazine, aperture entering arresting means on the other unit adapted to enter an aperture in an apertured member to arrest said relative motion with a corresponding record position in substantial alignment with said playing position, manually operable means for moving said apertured members individually into operated position to bring their apertures into alignment with said arresting means whereby said arresting means can enter said apertured member, automatic means for moving said apertured members individually into unoperated position with the apertures out of alignment with said arresting means, another arresting means on said other unit in alignment with the apertures of unactuated stop members adapted to enter each aperture progressively to stop said relative movement at each corresponding position, and means for rendering last said arresting means inoperative.

31. In an automatic phonograph, in combination, a unit including a record magazine adapted to accommodate a series of records, a unit including turntable means for rotating a record in playing position, means for causing relative motion between said units, a series of stops on one unit, each corresponding to a record position in said magazine, stop engaging means on the other unit adapted to engage a stop to arrest said relative motion with the corresponding record position in substantial alignment with said playing position, manually operable stop shielding means normally adapted to prevent said engag-

ing means from engaging said stops, and means for manually operating said shielding means to permit said engaging means to engage the associated stops.

32. In an automatic phonograph, in combination, a movable record magazine accommodating a series of disc records, turntable means for rotating a record in playing position, means for moving said magazine, a series of stops, each corresponding to a record position in said magazine, stop engaging means movable with said magazine adapted to move therewith past said stops and engage a stop to arrest said magazine with a corresponding record position in substantial alignment with said playing position, means for transferring a record from said magazine to said turntable means, and manually operable stop shielding means normally adapted to prevent the engagement of said engaging means with the corresponding stop and means for manually operating said shielding means to permit said engaging means to engage the corresponding stop when operated.

33. In an automatic phonograph in combination, a movable record magazine accommodating a series of disc records, turntable means for rotating a record in playing position, means for moving said magazine, a series of stops, each corresponding to a record position in said magazine, stop engaging means carried by said magazine adapted to move therewith past said stops and engage a stop to arrest said magazine with a corresponding record position in substantial alignment with said playing position, means for

transferring a record from said magazine to said turntable means, a manually operable stop shielding means associated with each stop, means effective when one shielding means is operated to prevent said engaging means from engaging the stops, the shielding means of which are not operated, and to permit engagement with those stops, the shielding means of which are operated, and means for effecting the engagement of said engaging means with all stops sequentially when no stops have been operated.

34. In an automatic phonograph, in combination, a traveling member, arresting means thereon, a plurality of apertured elements corresponding to a series of positions of arrestment for said traveling member, said elements having their apertures in normal positions whereby the traveling member is progressively arrested at each of said positions, said elements being capable of individual manual displacement, means operably associated with said elements for rendering said arresting means inoperative with the undisplaced elements when one of the elements is displaced whereby said arresting means cooperates with the apertures in the displaced elements whereby said traveling member is adapted to move and stop at positions corresponding with each displaced element.

35. In an automatic phonograph, in combination, a record magazine accommodating a series of double faced disc records, turntable means for rotating a record in playing position, means for transferring records from said magazine to said turntable means, means to effect the playing of either face of any record in said magazine on said turntable means on either side of said playing position, including a manually operable apertured member corresponding to each face of each record in said magazine, said manually operable apertured members being arranged in

series, means movable along said series and adapted to enter the aperture of operated apertured members to be arrested thereby, and adapted to pass over unoperated apertured members when one or more have been operated and means controlled by the arrestment of said movable means to effect the playing of the record face corresponding to said operated apertured member.

36. In an automatic phonograph, in combination, means for rotatably supporting a record in playing position with the recording grooves on each side exposed, a magazine for accommodating a series of double faced disc records, automatic means for effecting relative movement between said supporting means and said magazine, automatic means for transferring a record from said magazine to said supporting means, arresting means for effecting alignment between said record transferring means and any record in said magazine, two separate pickup units, one positioned to contact and play the recording grooves on one side of said playing position and the other positioned to contact and play the recording grooves on the other side of said playing position, automatic means for returning a record from said supporting means to said magazine after playing, and automatic means for bringing either of said pickups into engagement with the recording grooves on their respective sides of a record, said automatic means being adapted to bring one of said pickups into playing relation with its face of a record when the said relative movement is in one direction and adapted to bring the other pickup into playing relation with its side of a record when the relative movement is in the opposite direction.

37. In an automatic phonograph, in combination, means for rotatably supporting a record in playing position with the recording grooves on each side exposed, a movable magazine for accommodating a series of double faced disc records, automatic means for moving said magazine past said playing position, a series of stop means adapted to arrest said magazine successively to locate the records therein in sequence in alignment with said record playing position, automatic means for transferring a record from said magazine to said supporting means, two separate pickup units, one positioned to contact and play the recording grooves on one side of said playing position, and the other positioned to contact and play the recording grooves on the other side of said playing position, automatic means for returning a record from said supporting means to said magazine after playing, and means controlled by the movement of said magazine to cause one of said pickups to be brought into contact with the recording grooves on one side of the playing position when the magazine moves in one direction and to cause the other of said pickups to be brought into contact with the recording grooves on the other side of said playing position when the magazine moves in the opposite direction.

38. In an automatic phonograph, in combination, a magazine containing a series of double faced disc records in face to face relation, centering means for engaging and rotating any record in said magazine in a plane established by said means with the playing grooves on both faces exposed, two pick-up units, means for bringing one of said units into contact with the playing grooves on the corresponding side of said plane, radially to one side of said center-

ing means, means for bringing the other said unit into engagement with the playing grooves on the other side of said plane, radially to the other side of said centering means, trip means for instituting a record changing cycle, means constituting a common axis about which said pickups are adapted to pivot and means moving about said common axis with said pickups to actuate said trip means when said moving means moves beyond a certain point in either direction.

39. In an automatic phonograph, in combination, magazine means for supporting a series of double faced disc records in a generally vertical position, turntable means for rotating a record in a playing position established thereby, motor means for causing said magazine to travel, manually operable members corresponding individually to records in said magazine means and adapted to arrest the magazine with the corresponding records at a definite position, power actuated means for removing a selected record from said magazine to said turntable means for playing, a pickup unit positioned on one side of said plane, another pickup unit positioned on the opposite side of said plane, power actuated means for causing first said pickup to engage the corresponding side of a record on said turntable means while the other is disengaged, power actuated means for causing second said pickup to engage the opposite side of the record while the first said pickup is disengaged, power actuated means for returning the record to its original place in said magazine after playing, trip means for instituting a record changing cycle, means constituting a common axis about which said pickups are adapted to pivot, and means moving about said common axis with said pickups to actuate said trip means when said moving means moves beyond a certain point in either direction.

40. In a phonograph, in combination, turntable means for rotating a double faced disc record in a vertical plane, a generally V-shaped pickup supporting member, a pickup carried at one end of said V member on one side of said plane, another pickup carried at the other end of said V member on the other side of said plane, a pivot near the apex of said V member establishing a common rotational axis for both said pickups as they move over the record in playing, means for effecting engagement of either pickup with the corresponding side of the record, and counterbalance means carried by said V member counterbalancing both pickups around said axis.

41. In a phonograph, in combination, turntable means for rotating a double faced disc record in a plane, a generally V-shaped pickup supporting member, two separate pickups, one carried at each end of said V member on opposite sides of said plane, a pivot near the apex of said V member establishing a common rotational axis for both pickups, means for causing either of said pickups to engage the corresponding face of a record carried by said turntable means or move clear thereof, means for causing said pickup actuating means to move generally parallel to said axis to engage or disengage said pickups, and means for rotating said pickup actuating means around said axis to communicate its effect to either pickup selectively.

42. In an automatic phonograph, in combination, a magazine having a plurality of spaces

for a corresponding number of records, turntable means adapted to support a record for reproduction in a playing position, means for effecting relative motion in opposite directions between the turntable means and the magazine whereby each record position may be aligned with the playing position, displaceable stops corresponding in number to twice the number of records, each stop corresponding to the recording on one side of a record, and a pair of arresting members movable with the movable element of the machine for effecting alignment of the playing position with the record positions, one of said arresting members being adapted to engage displaced stops corresponding to the recordings on one side of the records when the movement is in one direction and the other of said arresting members being adapted to engage displaced stops corresponding to the recordings on the other sides of the records when the movement is in the opposite direction.

43. In an automatic phonograph, in combination, a magazine having a plurality of spaces for a corresponding number of records, a transfer member adapted to remove a record from the magazine, means for effecting relative movement between the magazine and transfer member in opposite directions, two spaced apart sets of selectors corresponding respectively to recordings on opposite sides of the records, and a pair of arresting members associated with said stops and movable with the movable element of the machine, one of said arresting members being associated with and movable relative to one of said sets and the other being associated with and movable relative to the other of said sets, and one of said arresting members being effective to arrest said movable element in one direction of said relative movement and the other in the opposite direction of said relative movement.

44. In an automatic phonograph, in combination, turntable means, a magazine adapted to accommodate a series of disc records, driving means for causing relative motion between said magazine and said turntable means through a limited distance and back again to effect substantial alignment between any record in said magazine and said turntable means, power means for driving said turntable means in either direction, means for actuating said driving means from said power means, and means for reversing said power means at each end of the relative travel between said magazine and said turntable means, thus reversing the turntable means, the driving means, and the direction of said relative motion.

45. In an automatic phonograph, in combination, means for rotatably supporting a record in playing position with the recording grooves on each side exposed, two separate playing arms, one positioned to contact and play the recording grooves on one side of said playing position and the other positioned to contact and play the recording grooves on the other side of said playing position, means providing pivotal support for each player arm about a common axis whereby each player arm may move about said axis over said record during playing, means movable on said common axis for controlling the engagement of the record by one or the other of said player arms.

46. In an automatic phonograph, in combination, a magazine, turntable means, means for transferring a record between said magazine and

5 said turntable means, a reversible motor for rotating said turntable means in either direction to adapt the record for playing on either side, a cam driven by said motor in either direction, a pivoted member engaged by said cam for operating said transferring means, said cam being effectively symmetrical with respect to said pivoted member whereby the transferring operation is similarly effected when the motor is operating in either direction.

10 47. In an automatic phonograph, in combination, turntable means, a magazine adapted to accommodate a series of disc records, drive means for causing relative motion between said magazine and said turntable means through a limited distance and back again to effect substantial alignment between any record in said magazine and said turntable means, power means for driving said turntable means in either direction, means for rotatably driving said drive means from said power means, and means for reversing said power means at each end of the relative travel between said magazine and said turntable means, thus reversing the turntable means, the drive means, and the direction of said relative motion.

15 48. In an automatic phonograph, in combination, a unit including a record magazine adapted to accommodate a series of records, a unit including a turntable means for rotating a record in playing position, means for causing relative motion between said units, a series of apertured stop members on one unit, each corresponding to a record position in said magazine, aperture entering arresting means on the other unit adapted to enter an aperture in an apertured member to arrest said relative motion with a corresponding record position in substantial alignment with said playing position, manually operable means for moving said apertured members individually into operated position to bring their apertures into alignment with said arresting means whereby said arresting means can enter said apertured member, automatic means for moving said apertured members individually into unoperated position with their apertures out of alignment with said arresting means, another arresting means on said other unit in alignment with the apertures of unactuated stop members adapted to stop said relative movement at each corresponding position, and means operated by any actuated apertured member for rendering last said arresting means inoperative.

20 49. In a phonograph, in combination, rotatable record supporting means adapted to support a record with the recorded surface on both sides exposed, reproducing means having needle means adapted to project in opposite directions to contact either face of a record on said supporting means, a magazine adapted to contain a series of records in face to face relation, means for effecting relative movement between the magazine and the record supporting means in two opposite directions to effect registry between any record in said magazine and said supporting means, means for transferring a record in registry from said magazine to said supporting means and back to said magazine after playing, and means controlled by said movement effecting means to cause the needle means to move in one direction to contact one side of a record on said supporting means when said relative movement is in one direction and to cause the needle means to move in the opposite direction to contact the other side of a record on said supporting means

when said relative movement is in the opposite direction.

50. In an automatic phonograph, in combination, a magazine adapted to accommodate a plurality of records in vertical face to face relation, a record support for rotating a record in a definite vertical playing plane substantially parallel to a plane for a record in said magazine, means for rotating said support in either direction, movable means for affecting the alignment of any record in said magazine and said playing plane, said movable means adapted to move in one direction when said record support is rotated in one direction and to move in the opposite direction when said record support is rotated in the opposite direction, means for transferring a record from said magazine to said record support by a horizontal edgewise rolling movement substantially in said playing plane, reproducing means having needle means adapted to project in opposite directions, and means for causing said needle means to move in one direction to contact one face of a record on the record support and in the opposite direction to contact the other face of a record on said support.

51. In an automatic phonograph, in combination, a magazine for records, record supporting means adapted rotatably to support records for playing, means to effect relative movement between said magazine and said record supporting means, two separate needle means adapted to project in opposite directions and adapted to cooperate with opposite sides of records on said supporting means, a support for movably mounting said needle means for pivotal movement toward and away from records on said record supporting means, means mounting said support for pivotal movement about an axis perpendicular to said records on said supporting means, means for transferring records between said magazine and said record supporting means, automatic power means for actuating said transferring means and for then rendering one of said needle means effective on one side of said records, a trip actuating member mounted upon and pivotally movable with said pivotally movable support about said axis perpendicular to the records, and means including trip means actuated by said actuating member at the ends of said records for causing said power means to remove said one needle means from said records and to place said other needle means in playing contact with the other side of said records.

52. In an automatic phonograph, in combination, a magazine for records, record supporting means adapted rotatably to support records for playing, means for effecting relative motion between said magazine and said supporting means in one direction and in the opposite direction, needle means adapted to project in opposite directions and adapted to cooperate with opposite sides of records on said supporting means, means for transferring records between said magazine and said record supporting means, and automatic means effective at the end of said relative movements for rendering said needle means effective to play one side of the records when the relative movement is in one direction, and for rendering said needle means effective to play the opposite side of the records when the relative movement is in the opposite direction.

53. In an automatic phonograph, in combination, a movable magazine for records, record supporting means adapted rotatably to support rec-

ords for playing, two separate pickups facing in opposite directions and adapted to cooperate with opposite sides of records on said supporting means, means for transferring records between said magazine and said record supporting means, selector means individual to the recordings in the magazine adapted for operation to select any plurality of recordings, trip means for starting a record changing cycle, automatic means for performing said cycle, power means for driving said automatic means, means common to both pickups for shifting either of said pickups into playing relation with a record on said supporting means, said common means adapted to be driven by said power means and means common to both of said pickups for tripping said trip means when either of said pickups approaches the center of a record.

54. In an automatic phonograph, in combination, a turntable for rotatably supporting a record in playing position with the recording grooves on each side exposed, means for supporting a plurality of records in a storage position, means to cause a record to be moved from said storage position on to the turntable, a reversible electric motor for rotating the turntable in either direction, a pair of reproducing means permanently located one at each side of said turntable, and means driven by said motor for bringing said reproducing means into initial playing relation on either side of the record playing position defined by the first said means.

55. In an automatic phonograph, in combination, means for rotatably supporting a record in playing position with the recording grooves on each side exposed, means for rotating the first said means in either direction, a pair of reproducing means positioned one permanently on each side of said playing position and means driven by the rotating means in one direction or the other for selectively bringing one or the other of said reproducing means into initial playing relation on its side of the record playing position.

56. In a phonograph, in combination, turntable means for rotating a double-faced disc record, a pair of pickup supporting arms, a pair of pickups supported by said arms, means defining an axis substantially normal to the plane of rotation of said turntable means around which both of said arms are adapted to pivot, means defining separate axes parallel to the plane of rotation of said turntable means about which said arms are adapted to pivot independently of each other, common means for moving either one or the other of said arms so as to bring their respective pickups into contact with one side of a record on said turntable means, power means adapted selectively to cause rotation of said turntable means in either direction, and means controlled by the direction of rotation of said power means to determine the pickup to be moved into playing position.

57. In an automatic phonograph, means for supporting and rotating a record with the playing grooves on both sides exposed, means for supporting a plurality of records in a storage position, means for effecting the transfer of a record from one of said positions to the other of said positions, two separate reproducers positioned permanently one on each side of said record rotating means, means for moving one reproducer in one direction into engagement with one side of a record on said record rotating means

and for moving the other reproducer in the opposite direction into engagement with the other side of the record, automatic mechanism for operating said transfer effecting means and for operating said reproducer engaging means, motor means for driving said automatic mechanism, means for starting the drive of said automatic mechanism by said motor means, and means common to both reproducers and movable with both reproducers and actuated by either reproducer at the end of the playing grooves on either side of the record for actuating said starting means to start said automatic mechanism, to transfer a record, and to bring a reproducer into engagement therewith.

58. In an automatic phonograph, means for supporting and rotating a record with the playing grooves on both sides exposed, means for supporting a plurality of records in a storage position, means for effecting the transfer of a record from one of said positions to the other of said positions and subsequently back to the first of said positions, two separate reproducers mounted permanently, one on each side of said record rotating means upon a common movable support, means for moving one reproducer in one direction into engagement with one side of a record on said record rotating means and for moving the other reproducer in the opposite direction into engagement with the other side of the record, automatic mechanism for operating said transfer effecting means and for operating said reproducer engaging means, motor means for driving said automatic mechanism, and means movable with said common movable support for starting the drive of said automatic mechanism by said motor means.

59. In a phonograph, in combination, turntable means for rotating a record in a plane established thereby with the playing grooves on both faces of the record exposed, a first pickup located at the one side of said plane and a second pickup located at the other side of said plane, supporting structure for both said pickups movable about a common axis perpendicular to said plane whereby said pickups are enabled to move in said plane and follow the grooves in the record during playing, other supporting structure on said first mentioned structure pivotally supporting said pickups for movement into and out of engagement with a record in said plane, said last mentioned supporting structure being located to one side of said common axis, and pickup actuating means located coaxially of and axially movable along said common axis for effecting pivotal movement of said pickups toward and away from said plane.

60. In an automatic phonograph, in combination, record supporting means adapted rotatably to support records in a single playing plane with

the recording grooves on both sides exposed, two separate pickups positioned permanently one on each side of said playing plane, a common support for said pickups movable about an axis perpendicular to said playing plane, said pickups being mounted on said support for common movement with said support about said axis whereby said pickups follow the record grooves when moved into contact therewith, means mounting 10 said pickups on said support for pivotal movement toward and away from said playing plane whereby said pickups are movable into contact with the record grooves, a member movable coaxially of and along said perpendicular axis for effecting pivotal movement of the pickups toward and away from said playing plane, a trip actuating member mounted on and movable with said common pickup support about said perpendicular axis, trip means actuated by said 20 actuating member when the center of a record is approached by the pickup in contact with record grooves, and power means controlled by said trip means for effecting movement of said coaxially movable member to move out of contact with the record the pickup in contact with the record grooves when it approaches the center of a record.

61. In an automatic phonograph, in combination, a record supporting means adapted rotatably to support records in a single playing plane with the recording grooves on both sides exposed, power actuated transfer mechanism for effecting the transfer of records from said record supporting means, two separate pickups positioned 30 permanently one on each side of said playing plane, a common support for said pickups movable about an axis perpendicular to said playing plane, said pickups being mounted on said support for common movement with said support about said axis whereby said pickups follow the record grooves when moved into contact therewith, means mounting said pickups on said support for pivotal movement toward and away from said record playing plane whereby said pickups 35 are movable into contact with the record grooves, power actuated means for effecting pivotal movement of the pickups toward and away from said playing plane, a trip actuating member mounted on and movable with said common pickup support about said perpendicular axis, trip means actuated by said actuating member when the center of a record is approached by a pickup 40 in contact with the record grooves, and power means controlled by said trip means for effecting movement of said power actuated means to move the pickup out of contact with the record grooves when it approaches the center of a record and for effecting operation of said transfer mechanism.
